CALCULATING MACHINE

Harry L. Lambert, East Rochester, N. Y., assignor,
by mesne assignments, to The National Cash
Register Company, Dayton, Ohio, a corporation
of Maryland

Application April 3, 1945, Serial No. 586,359

13 Claims. (Cl. 235—60.31)

1

This invention relates to calculating machines and the like and more particularly to novel control means therefor, for controlling various types of operations for machines of this character.

In many machines of the type shown and described herein, there are provided manually operable devices operable to predetermine the several types of operations through which machines of this type are adapted to be put, and in some machines such devices are mounted in the machine casing.

To eliminate or remove such manipulative control means from the casing is one of the objects of this invention.

Another object of the present invention is to provide a special novel control bank of keys for determining and controlling the various types of operations, such as add, non-add, subtract, total, and sub-total operations.

Another object is to provide a special mounting for manipulative control means and including a correction key or key release means.

A further object is to provide a novel interlocking means between all of said manipulative control means and between said means and the amount keys.

A further object is the provision of novel machine release and control means operable from any of said control keys.

Another object is to provide a novel means to control the totalizer engaging means under control of said control keys.

Another object is the provision of means operable under control of the add motor bar to cause the machine to make a sub-total operation instead of an add operation.

A further object is the provision of novel non-add control means.

A still further object is to provide a special novel control of the zero stop means during total and sub-total operations.

Another object is to provide means to cause a special operation of the machine release means during total and sub-total operations.

With these and other incidental objects in view, the invention includes certain novel features of construction and combinations of parts, the essential elements of which are set forth in appended claims and a preferred form or embodiment of which is hereinafter disclosed with reference to the drawings which accompany and form a part of this specification.

Of said drawings:

Fig. 1 is a perspective view of the machine embodying the present invention.

Fig. 2 is a section taken alongside one of the amount banks looking toward the left of the machine.

Fig. 3 is a detail of an amount key showing its control over the zero stop.

Fig. 4 is a detail view, in enlarged scale, of a part of the totalizer transfer mechanism and adding rack and includes the transfer trip restoring means.

Fig. 5 is a plan view of a portion of the machine with the keyboard removed.

Fig. 6 is a view of the right side of the machine, showing the bank of control keys and a part of the mechanism operated thereby to release the machine and control the totalizer engaging and disengaging mechanism.

Fig. 7 is a plan view showing the totalizer engaging control and a part of the machine release means.

Fig. 8 is a view outside the right side frame of the machine looking toward the left, showing a part of the totalizer engaging control, subtract control, key release, and machine driving mechanism.

Fig. 9 is a plan view, partly in section, of a portion of the control bank, non-add control, and zero stop control during totaling operations.

Fig. 10 is a detail view of the hammer restoring means and ribbon shift pawl for shifting the ribbon from black to red during subtract operations.

Fig. 11 is a view taken inside the left side frame, showing the machine drive, the machine release mechanism, and part of the subtract control mechanism.

Fig. 12 is a detail of a part of the motor drive.

Fig. 13 shows the interlock between the amount keys and the total keys.

Fig. 14 shows the interlock between the amount keys and the total keys and a part of the total engaging control mechanism.

Fig. 15 shows the totalizer engaging means, a part of the control therefor, a portion of the zero stop control means, and the machine release for the second machine cycle of a total taking and sub-total taking operation.

Fig. 16 is a detail of the latching device for the totalizer engaging control means.

Fig. 17 is an enlarged edge view, partly in section, showing the interlocks between the keys of the control bank and a part of the zero stop controls.

Fig. 18 shows a part of the totalizer engaging mechanism, the restoring means for the rack

levers and diverging levers and also the paper feed mechanism and the control therefor.

Fig. 19 shows the non-add control for the totalizer and also the symbol printing means.

FRAMEWORK AND CASING

Most of the mechanism of the machine is mounted on or between a left side frame 30 (Figs. 2, 5, and 11) and a right side frame 31 (Figs. 5 and 6), which side frames are tied together near their lower edges by cross braces 32 and 33, having ears 34, by means of which they are bolted to the side frames 30 and 31.

At the rear, the frames 30 and 31 are tied together by a brace 35, having ears 36, by means of which the brace 35 is bolted to the side frames. A tie bar 37, having ears 38, is used to properly space the side frames 30 and 31 near their extreme forward ends. A bar 39 (Figs. 2 and 5) is also used to properly space the side frames 30 and 31 near their upper front portions. This bar has secured to it a plate 40, which also acts as a spacer and helps to make the bar 39 rigid.

The machine is enclosed in a cabinet or casing designated generally as 45, which casing consists of a base 46 (Figs. 1 and 2), which is secured to the brace 33 and to the tie bar 37, a left side section 47, a right side section 48, a back plate 49, a front plate 50, and a top plate 51. The top plate 51 is provided with an opening 52, covered with a glass 53 so that the totalizer may be readable by the operator of the machine.

OPERATING MECHANISM

The machine embodying the present invention is of the general type shown and described in the United States Letters Patent to H. C. Peters, Nos. 1,386,021 and 1,386,022, issued August 2, 1921, and 1,646,105, issued October 18, 1927; and also the United States Patent to N. White, No. 1,854,875, granted April 19, 1932.

All of said patents show machines operated by a handle; in other words, they are what are known in the art as hand-operated machines.

However, motors have been developed to operate machines of this type, and the machine shown in the present invention is operated by a conventional type of high-speed electric motor of a type extensively used for the operation of calculating machines, particularly adding machines, where the motor is given successive intermittent operations of a definite cycle in order to drive the drive shafts or operating mechanism of the machine for adding and all types of calculating operations which such mechanisms are adapted to perform. Such a motor replaces the usual hand crank which operates similar mechanism in a similar type of calculating mechanism.

The type of motor used in the present application is illustrated generally in the United States Letters Patent to Harry L. Lambert, No. 2,130,350, issued September 20, 1938.

A motor of this general type is indicated by dot-and-dash lines in Fig. 11 and is designated 60. Through proper gearing, this motor 60 operates a shaft 61 in a clockwise direction. Secured to this shaft is a notched disk or clutch member 62 adapted to be engaged by a clutch pawl 63 pivoted on a stud 64 carried by a lever 65, which is loosely mounted on the shaft 61. A spring 66 normally tends to rock the clutch pawl 63 clockwise, but is prevented from doing so due to the fact that the upper end of the pawl is held against a roller 67 on a lever 68 pivoted on a stud 69 mounted in the frame of the motor 60.

This lever 68, by means to be described hereinafter, is moved clockwise, and, when this occurs, the spring 66 rocks the pawl 63 clockwise, whereupon it engages the motor-driven notched disk 62, previously described.

Since the pawl 63 is pivoted on the lever 65, after engagement of the pawl 63 with the motor-driven disk 62, the pawl 63 and the lever 65 are given a complete clockwise rotation about the shaft 61.

Pivoted on a stud 71 carried by the lever 65 is a link 72 (Fig. 12), which carries a stud 73, to which are pivoted an arm 74 and an arm 75. The arm 75 is also pivoted on a rear drive shaft 76, which has secured thereto a drive collar 77, to which is secured a driving disk 78.

The arms 74 and 75 are connected by a strong coil spring 79, which holds a stud 80 on the arm 74 in a notch 81 of the drive disk 78. When the lever 65 is rocked clockwise (Fig. 12) one complete rotation, the link 72 rocks the arms 74 and 75 first counter-clockwise and then clockwise to normal position around the center of the shaft 76. Upon counter-clockwise movement of the arm 74, the stud 80, being held in the notch 81 by the spring 79, turns the drive shaft 76 counter-clockwise approximately 75 degrees, and then, as the arm 74 is restored clockwise to normal, the stud 80, through the notch 81, turns the drive shaft 76 clockwise to its normal position. The spring 79 causes the arms 74 and 75 to move as a unit around the center of the shaft 76 when they are driven by the link 72, the spring 79 creating a flexible drive between the motor 60 and the drive shaft 76.

The reason for this flexible drive is to protect the mechanism of the machine should the shaft 76 or any part of the machine be stopped during the machine operation, due to any cause whatsoever. In such a case—that is, the stopping of the shaft 76—the arm 74 then pivots on the stud 73 as the lever 65 and the link 72 complete their movement, thus disengaging the stud 80 from the notch 81, whereupon the spring 79 stretches and holds the stud 80 against a surface 82 of the drive disk until the link 72 starts its return movement (to the left in Fig. 12), at which times the arms 74 and 75 start their return clockwise movement about the center of the shaft 76, at which time the spring 79 will eventually cause the stud to again be seated in the notch 81 and restore the drive disk 78 to its normal position, shown in Fig. 12, from whatever position it had been stopped in during its counter-clockwise movement.

The lever 65 has secured thereto a cam 83, which, as the lever is being rotated clockwise, engages a roller 84 (Fig. 11) on the lever 68 and rocks this lever 68 counter-clockwise back to the position shown in Fig. 11, just prior to the time that the upper end of the pawl 63 reaches its home position, whereupon the roller 67 will be in the path of movement of the pawl 63, thus disconnecting the pawl from the notched driving disk 62, which, it will be recalled, is secured to the motor shaft 61, thus disconnecting the motor drive from the main shaft 76 at the end of the operation of the machine.

It might be well to state here that, as the lever 68 is moved clockwise from the position shown in Fig. 11 by means to be described hereinafter, a stud 85 thereon, through its contact with a finger 86 of an arm 87 pivoted on the stud 69, rocks this arm clockwise, whereupon an insulating roll 88 thereon closes a motor switch

89, which starts the rotation of the motor shaft 61.

A latch 25, pivoted on the motor frame 60, is normally held as shown in Fig. 11 by a cam 26 secured to the shaft 76. As the shaft 76 rotates counter-clockwise the cam 26 releases the latch 25 to the action of a spring 21 and said latch 25 then holds arm 87 in its moved position to hold the switch 89 closed until it is released by the cam 26 at the end of the operation.

When the lever 68 is rocked counter-clockwise to its normal position by the cam 83 through its contact with the roll 84, the stud 85 will move away from the finger 86, since the arm 87 is held by the latch 25.

When the latch 25 releases arm 87 the motor switch is free to open itself and break the circuit so that the motor will not continue to run after the end of the operation of the machine.

MAIN AND REAR DRIVE SHAFTS

The rear drive shaft 76, the driving of which by the motor has just been described, is mounted for oscillation in the side frames 30 and 31. A main drive shaft 100 (Figs. 5, 6, 7, and 11) is also supported for oscillation by the side frames 30 and 31 near the center part of the machine. This main shaft 100 receives its movement from the rear drive shaft 76 by the following described mechanism:

Secured to the rear drive shaft 76 is a drive plate 101, to which is pivoted a link 102, which is also pivoted to a drive plate 103 secured to the main drive shaft 100. In Figs. 6 and 8, the drive plate 103 is shown in its normal position resting against a flexible buffer 104 carried by a bracket 105 secured to the right side frame 31. When the shaft 76 is given its oscillation by the motor first counter-clockwise and then clockwise, as described above, the link 102 drives the plate 103 and the main shaft 100 first counter-clockwise and then clockwise to its normal position.

Secured to the main shaft 100 (Figs. 2 and 5) is an arm 106, to which is connected a strong spring 107, the front end of which is secured to a rod 108 held in notches in the front edges of the side frames 30 and 31 by the spring 107.

This spring 107 helps to restore the shaft 100 and also the shaft 76 in a clockwise direction to their normal positions after said shafts have been rocked counter-clockwise, which counter-clockwise movement stretches the spring 107 and puts it under considerable tension, so that, as the shaft 76 starts its return clockwise movement, the spring 107 will help to rock these two shafts 100 and 76 clockwise to their normal positions. Associated with the drive plate 101 (Fig. 8) is a bell crank 109 pivoted on a stud 110 secured to the frame 31. This bell crank 109 carries a roller 111, which is normally maintained in a depression 112 of the drive plate 101 under the influence of a strong spring 113, which is attached to the bell crank 109.

The drive plate 101 has a cam surface 114, which, as the plate 101 is rocked counter-clockwise, rocks the bell crank 109 counter-clockwise and stretches the spring 113 so that it is put under a considerable amount of tension, and therefore, as the plate 101 is rocked clockwise to its normal position as it nears the completion of its movement, the spring 113 has a tendency to cause the roller 111 to be forced into the notch 112 of the plate 101, so that, if the parts should become sluggish, then the spring 113 will return

the plate 101 and consequently the shaft 76 and also the main shaft 100 definitely to their home positions.

The drive plate 103 has thereon a hub 115 with a driving section 116, which is adapted to be inserted into a notch in the hub of a handle such as that shown in the above-mentioned Peters and White patents, should it be desired to operate the machine by hand directly from the main shaft 100. However, in order to do this, it is necessary to disconnect the link 72 from the driving lever 65, so that it will not be necessary to pull the motor around with the shaft 76 when the machine is being operated by hand directly by the oscillation or rocking of the shaft 100 by the handle.

No handle has been shown in this present application, but one is shown in each of the above-mentioned White and Peters patents, and therefore it does not in any way affect the invention disclosed herein.

KEYBOARD

The machine embodying the present invention is provided with a keyboard having eight banks 25 or rows of amount keys and a single bank of control keys. However, it is not intended to limit the invention to a machine having only eight banks of amount keys, because the number of banks of amount keys may vary without in any way affecting the invention.

Amount keyboard

Since the amount keyboard is quite similar to that which has been fully illustrated and described in the above-mentioned Peters patents, it is not thought necessary to go into a complete detailed description of the same herein, and therefore it will be but briefly described.

40 The amount keys 120 are depressibly mounted in a removable keyboard of the type shown in the above-mentioned patents. This keyboard consists of a top plate 121, a bottom plate 122 (Figs. 2 and 8), a left side plate 123, and a right side plate 124. These plates are tied together by a front cross bar 125 and a rear cross bar 126, so that the above-mentioned plates and two bars form a unit structure which can be readily removed from the machine.

45 The keyboard unit mentioned above is mounted on adjustable trunnions 127 (Figs. 2 and 8) by means of slots in the side plates 123 and 124, and at the front the side plates are notched to surround a rod 129. A pair of latches 130, pivoted on the side frames 30 and 31, hold the keyboard in position after it has been assembled in the machine on the trunnions 127 and the rod 129.

50 The keys 120 are guided in the top plate 121 and in the bottom plate 122. All of the amount keys are what is known in the art as flexible keys; that is, when a key in one bank is depressed, another key in the same bank may be depressed, which will release the first depressed key, which of course must occur prior to the time the machine is released. This type of key is very old and well known in the art. Each key 120 is provided with the usual restoring spring 131. Associated with each bank of keys is a rod 132 (Figs. 2 and 3) supported by the front and rear bars 125 and 126, upon which is pivoted a zero stop 133 carrying the usual bar 134 associated with all keys in the row, so that the depression of any key in the row will rock the zero

55 stop 133 counter-clockwise (Fig. 3) to move it

into an ineffective position relative to the differential mechanism to be described hereinafter.

As shown in Figs. 2 and 13, the zero stop bar 134 has an ear 135, which is pivoted on the rod 132. The usual retaining bar 136 (Figs. 2 and 13) is also pivoted on the rod 132 to cooperate with the keys in the bank adjacent to the bank shown in Fig. 2. A torsion spring 137 operates on the zero stop bar 134 and the retaining bar 136 to hold them at all times against the sides of the key stems.

The usual locking bar or detent 138 (Figs. 2 and 3) is provided for each bank of keys, which in the well-known manner is moved over a projection 139 on the depressed key by means of a spring-pressed bar 140 after the machine has been released.

At the beginning of an operation of the machine—that is, immediately after the motor has been released to drive the machine—the locking detents 138 (Figs. 2 and 3) for each bank of keys are rocked to positively lock all keys in either their depressed or undepressed positions until they are released near the end of the operation at the proper time. The locking detents, as mentioned above, are moved by the bar 140 (Fig. 8), which is held in the position shown herein by a lever 141 pivoted on a stud 142 carried by the right side plate 124 of the key bank. A spring 143 normally holds the lever 141 against a roller 144 carried by the operating plate 103. When the plate 103 is rocked counter-clockwise in the manner described previously, the roller 144 is lowered, and consequently the spring 143 will rock the lever 141 clockwise, whereupon a spring (not shown) will move the bar 140 to rock the locking detents 138 to lock all keys in their depressed and undepressed positions.

There is an interlocking means controlled by the bar 140 to prevent the drive shafts 76 and 100 from operating shortly after their initial movements, in case any amount key 120 is only partially depressed. This means comprises a lever 90 (Fig. 8) pivoted on the side frame 31 by a screw stud 91. An arm 92 of the lever 90 is normally held against the roller 144 by a spring 93, and a finger 94 of the lever is just above a lug 95 on the bar 140. When a key 120 is fully depressed, the lug 95 moves out from under the finger 94, and when the roller 144 is moved down by the plate 103, spring 93 moves the lever 90 counter-clockwise, whereupon the finger moves down alongside the lug 95, and at the same time a node 96 on the lever is moved out of the path of a block 97 on the plate 103. The plate 103 can then make its full counter-clockwise movement. When the finger 94 is down alongside the lug 95, the depressed keys are also prevented from being released. The roller 144, upon return clockwise of the plate 103, rocks the lever 90 to raise the finger 94 above the lug 95, and then the bar 140 can be restored to normal position by the lever 141 contacting the end of the bar, which is beveled for that purpose.

The left end of the lever 141 carries the usual by-pass pawl 145, which cooperates with a stud 146 on a key release lever 147, which has a bail 148 pivoted to the side plates 123 and 124 of the key frame. This bail 148 is forked to project between the bars 134 of the zero stop pawls 133 and the retaining detents 136, so that, when the arm 147 is rocked clockwise by the pawl 145, the zero stops 133 will be moved counter-clockwise (Figs. 3 and 13) and the retaining detent bars 136 will be moved clockwise, so that any key

which has been depressed during the operation of the machine will be released.

The pawl 145, being attached to the lever 141, by-passes the stud 146 as the lever 141 is moved clockwise by the spring 143 when the roller 144 is moved downwardly. Near the end of the operation, as the roller 144 rises as the drive plate 103 is rocked clockwise to its normal position, the roller 144 contacts the lever 141 and rocks it counter-clockwise, whereupon the pawl 145, through its contact with the stud 146, rocks the key release lever 147 and its associated bail 148 to release all depressed keys near the end of the operation of the machine.

Repeat mechanism

At times it may be desirable to have repeat operations, and therefore the machine is provided with the usual repeat lever 149 (Figs. 1 and 8), which is pivoted on a stud 150 carried by the right side plate 124, as shown in Fig. 8. Secured to the repeat lever 149 is the usual alining plate 151, which cooperates with a stud 152 in a spring-drawn arm 153 pivoted on the stud 142.

When it is desired to prevent the release of any depressed key 120 by the lever 141 at the end of the operation of the machine, the repeat lever 149 (Fig. 8) is moved clockwise, whereupon a surface 154 of the alining plate 151 is moved directly above a stud 155 on the lever 141, so that, when the roller 144 is moved out of the path of the lever 141, the spring 143 will move the lever 141 a shorter distance than usual because the stud 155 will contact the surface 154 of the alining plate 151, which holds the by-pass pawl 145 below the stud 146. Consequently, when the lever 141 is rocked counter-clockwise by the roller 144 near the end of the operation of the machine, the pawl 145 being below the stud 146, there will be no movement of the key release lever 147 and its bail 148, and therefore any key which has been depressed at the beginning of the operation of the machine will remain depressed for a subsequent operation of the machine whenever the repeat lever 149 has been moved clockwise from that position, shown in Fig. 8.

Control key bank

As mentioned above, the machine is provided with a special control bank, which in the present invention is mounted to the right of the regular keyboard and on the outside of the right-hand side frame 31, so that the keys and bars of this special control bank project through the right side 48 of the machine casing.

All of the keys or bars of this special control bank are motorized keys; that is, when depressed they will operate mechanism to release the motor so that the machine will go through its operation without the necessity of depressing a special motor bar. This is true in connection with all keys except the correction key.

Referring now to Figs. 1 and 6, the keys of this control bank are as follows: a correction key 160, marked "C," is the first key in the bank. Next, there is a bar 161 having thereon a plus sign near its top, and at the front end of the bar are the words "Sub total." The next key 162 is a subtract key and is marked with a subtract sign. Key 163 is the non-add key and is so marked. Key 164 is the total key and bears the inscription "Total."

All of these keys 160 to 164 are provided with keysystems 165 to 169, respectively, which have slots to surround studs 170 mounted in a key

frame 171 supported on two studs 172 carried by the right side frame 31. By means of the studs 170, all of the keys 160 to 164 inclusive are guided and supported on the special key frame 171. Each of the keys has the usual restoring spring 173.

Correction key

The correction key 160 carries a stud 174, which engages the lower arm of a bell crank 175 (Figs. 6, 8, and 17) pivoted on a stud 176 carried by the frame 171. The upper arm of the bell crank 175 cooperates with a stud 177 on the key release lever 147, previously described. This bell crank 175 is held against the stud 174 by a spring 178. When the correction key 160 is depressed, the stud 174 rocks the bell crank 175 counter-clockwise, whereupon its upper arm, through the stud 177, rocks the key release lever 147 and its associated bail 148, thus releasing any and all keys which have been depressed, if this key 160 is depressed before any of the keys 161 to 164 inclusive.

Key interlocks

As a matter of fact, the key 160 cannot be depressed after the depression of any one of the keys 161 to 164, due to a plate 179 (Fig. 6), which cooperates with a stud 180 in the correction key stem 165. There is a stud 180 in the key stems 166, 167, and 168, which cooperate with plates 181, 182, and 183. The plates 179 to 183 form what is known in the art as a crowding key lock, thus preventing the depression of any one of the keys 160 to 164 when any other one of them has been fully depressed. These crowding key lock plates 179, 181, 182, and 183 are slidably mounted on studs 184 carried by the key frame 171.

Pivoted on the left-hand one of the studs 184, which supports the plate 183, is an arm 185 having a slot surrounding the stud 180 on the total key stem 169. The arm 185 also has an extension 187, which carries a stud 186, which cooperates with the plate 183 in the same manner that the studs 180 of the key stems 165 to 168 cooperate with associated plates, 179, 181, or 182. In other words, when the total key 164 is depressed, the arm 185 is rocked clockwise, whereupon the stud 186 moves the plate 183 to the left and at the same time moves the plates 182, 181, and 179 to the left, so that none of the keys 160 to 163 inclusive can be depressed whenever the key 164 is depressed.

For example, when the subtract key 162 is depressed, its stud 180 forces itself between the two plates 181 and 182, thus forcing the plate 183 to the right to prevent depression of the key 164. The plate 182 prevents depression of the key 163, the plate 181 prevents depression of the key 161, and the plate 179 prevents depression of the key 160. Thus, it can be seen that, when any of the keys 160 to 164 is depressed, its associated stud 180 controls the operation of the crowding key lock plates 179 to 183, so that only one of the keys 160 to 164 may be depressed for any one single operation of the machine.

Motor release

As mentioned above, when any one of the keys 161, 162, 163, or 164 is depressed, it releases the motor for operation. This mechanism will now be described with particular reference to Figs. 5, 6, and 11.

Pivoted on a stud 191 (Fig. 11) of the previously described lever 68 is a link 192 carrying a stud 193, to which is connected the left end of a lever 194 (Fig. 5), which is pivoted on a screw stud 195

mounted in the brace 32. A spring 196, stretched between the lever 194 and a stud on the brace 32, holds a right arm 197 of the lever 194 against the side of a lug 198 (Fig. 15) on an arm 199 pivoted on a stud 200 carried by the key frame 171. The arm 197 is guided by a slot 201 in the right side frame 31, as shown in Fig. 8. The arm 199 is also held upwardly against the bottom side of the arm 197 by a spring 202, stretched between a flange 203 of the arm 199 and a stud carried by the key frame 171.

The spring 196 also tends to rock the lever 68 clockwise to release the clutch pawl 63 and at the same time, through the stud 85, tends to rock the contact roller arm 86-87 clockwise to close the motor switch 89.

Whenever the arm 199 is rocked clockwise (Fig. 6), the lug 198 is moved below the path of the arm 197 of the lever 194, whereupon the spring 202 196 rocks the lever 194 and the arm 197 counter-clockwise, as viewed in Fig. 5, which moves the link 192 toward the front of the machine (to the left as viewed in Fig. 11), thus rocking the lever 68 to release the clutch pawl 63 to the action of its spring 66 and at the same time, through the stud 85, rocks the arm 87 clockwise, whereupon the roller 88 closes the motor switch 89 to release the motor for operation, so that the shaft 61 may be rotated, and, through the mechanism shown in Figs. 11 and 12, drives the rear drive shaft 76 in the manner previously described.

During the clockwise movement of the lever 65 in the manner previously described, it will be recalled that its cam 83, by contacting the roller 84 of the lever 68, rocks the lever 68 counter-clockwise back to normal position, which at the same time moves the link 192 to the right, as viewed in Fig. 11, thus rocking the lever 194 and the arm 197 clockwise to bring the arm 197 into the position shown in Figs. 6 and 15, wherein it lies to the left of the lug 198 on the arm 199, in which position it is locked, as the spring 202 will rock the arm 199 counter-clockwise just as soon as the arm 197 moves to the left (Fig. 15) off the top of the lug 198, the parts then being in their normal positions.

The means for rocking the arm 199 clockwise in the manner just described, to release the machine for operation under control of the keys 161, 162, 163, and 164, will now be described, referring to Fig. 6.

When the add and sub-total bar 161 is depressed, a finger 210 thereon engages a stud 211 on the arm 199, and continued depression of the bar 161, through the finger 210 and the stud 211, rocks the arm 199 clockwise to release the arm 197 from the lug 198 for the purpose described previously.

Whenever the machine is being used for adding operations, the bar 161 is depressed and immediately released, whereupon the machine is driven through one complete cycle of operation by the motor 60.

However, when it is desired to make a sub-total operation following an item-entering operation, there is means, to be described hereinafter, which will cause the machine to go through two complete machine cycles following the item-entering cycle to complete the sub-total operation when the bar 161 is depressed and held depressed until after the item-entering cycle has been completed. This will cause the machine to take a sub-total from the totalizer to be described hereinafter and to print that sub-total on a tape which will also be described later.

In other words, if a series of items is to be entered and it is desired to obtain the sub-total therefrom, as each item is set up on the keyboard by depression of the amount keys 120 and the bar 161 is depressed to release the motor for each item, each of the several items will be successively added into the totalizer. When the last item is about to be entered, the operator sets this item up on the keyboard and depresses the key 161, holding it depressed through the cycle of operation wherein the amount, according to that represented by the depressed keys, is added into the totalizer, which causes an immediate two-machine-cycle operation of the machine, which, due to other mechanism to be described hereinafter, under control of this key 161 will cause the subtotal of the several items to be printed from the totalizer.

When it is desired to release the machine for a subtract operation—that is, to have an amount set up on the keyboard subtracted from the totalizer—the operator depresses the subtract key 162. The key stem 167 of this key has a finger 212, which also lies above the stud 211 of the arm 199, and consequently, when the key 162 is depressed, the finger 212, by its contact with the stud 211, rocks the arm 199 clockwise to remove the lug 198 thereof from the path of the arm 197, so that the spring 196 may rock the lever 194 counter-clockwise (Fig. 5) to release the machine for, in this particular case, a subtract operation. The means for causing an amount set up on the keyboard to be subtracted will be described hereinafter.

The means for rocking the arm 199 to release the machine for operation upon depression of the Non-Add key 163 comprises the following mechanism: Pivoted on a stud 213 (Fig. 6), carried by the key frame 171, is a lever 214 having a finger 215, which normally lies on top of the stud 211 of the arm 199. Pivoted to the lever 214 is a link 216, which in turn is pivoted to a bell crank 217 pivoted on a stud 218 mounted in the frame 171. The key stem 168 of the Non-Add key 163 has a stud 219 in such a position that, when the Non-Add key 163 is depressed, the stud 219 will contact and rock the bell crank 217 counter-clockwise, whereupon the link 216 rocks the lever 214 counter-clockwise, and the finger 215, by its contact with the stud 211, rocks the arm 199 to move the lug 198 out of the path of the arm 197, so that the motor 60 may be released to operate the machine in the manner described above.

The means for rocking the arm 199 under control of the Total key 164 will now be described. Pivoted on the stud 218 is a lever 220, which is pivoted to an arm 221 of the lever 214. The key stem 169 of the Total key 164 has a finger 222 carrying a stud 223. When the Total key 164 is depressed, the stud 223 contacts and rocks the lever 220 clockwise, which in turn, through its connection with the lever 214, rocks the lever 214 counter-clockwise, whereupon the finger 215, by its contact with the stud 211, rocks the arm 199 clockwise to release the motor for operation in the manner described previously.

It might be well to state here that, whenever the Total key 164 is depressed, the machine will automatically make two machine cycles to complete a total-taking operation, the first machine cycle being a so-called idle cycle to restore to normal position any tripped transfer devices in the totalizer.

In order to have the machine then released for the second successive machine cycle without again depressing the key 164, the machine is pro-

vided with a means for retaining the arm 199 depressed, so that the arm 197 will not become latched behind the lug 198 when the cam 83 restores the lever 68 (Fig. 11) at the end of the first machine cycle of the operation, which, it will be recalled, moves the link 192 to the right and at the same time rocks the lever 194 and the arm 197 clockwise (Fig. 5) to bring the arm 197 into such position that the spring 202 may rock the arm 199 counter-clockwise to again latch the arm 197 in the position shown. However, since the arm 199 is retained in its depressed position by means to be described hereinafter, the rocking of the lever 194 and the arm 197 clockwise by the cam 83 through the lever 68 is merely an idle operation, and consequently the spring 196 will again immediately rock said lever 194 and arm 197 counter-clockwise (Fig. 5) to cause the motor 60 to drive the machine through an immediate second machine cycle.

Interlock between amount keys and total key

To prevent the total key 164 from being depressed while any one of the amount keys 120 is depressed, there is provided an interlocking mechanism which will now be described with particular reference to Figs. 6, 13, 14, and 17.

Secured to the key frame 171 is a bracket 231, on which is pivoted an arm 232 held in the position shown in Fig. 17 by a light torsion spring 233, which is wound around a post 234 on the bracket 231 and which has one end overlying the arm 232 and also bent down, so that the general tendency of the spring 233 is to hold the arm in the position shown in Fig. 17, wherein a node 235 thereon is held against a flange 236 of a bar 237 slidably mounted in the rear of the keyboard frame and being guided by the side plates 123 and 124. This bar 237 extends all the way across the keyboard, and adjacent each of the bars 134 of the zero stops 133 there is a flange 238 (Fig. 13) in such a position that, whenever the zero stop 133 of any particular bank is rocked, the bar 237 will be moved to the right, as viewed in Fig. 13, by the bar 134 on the zero stop 133. This will occur whenever a key is depressed in any key bank. In other words, the first key depressed, regardless of the denominational bank in which it is depressed, or regardless of the significant value of that key, will move the bar 237 to the right, as viewed in Fig. 13.

When this occurs, the flange 236 of the bar 237 (Fig. 17), by its contact with the node 235 of the arm 232, will rock the arm 232 clockwise against the action of the spring 233 and position a bent-over finger 239 thereon immediately below the extension 187 of the arm 185, which, it will be recalled, is connected by a slot to the pin 180 of the total key stem 169, and consequently, when this bent-over finger 239 of the arm 232 has been moved beneath the extension 187 of the arm 185, it becomes impossible to depress the total key 164.

Conversely, when the total key 164 has been depressed, the extension 187 of the arm 185 prevents clockwise movement of the arm 232, thus locking the zero stops 133 against movement from their normal position and preventing depression of the amount keys.

Control key locks

Associated with the keys 161, 162, 163, and 164 (Figs. 6 and 17) is a device for locking the depressed one of said keys in its depressed position until near the end of the operation of the ma-

chine, and at the same time preventing depression of any other of said keys when any one of them is depressed.

This mechanism comprises a locking slide 250 mounted on the previously described studs 184 on the key frame 171. This slide 250 carries a stud 251, to which is connected the upper end of a lever 252 pivotally mounted on a stud 253 supported by the key frame 171. The lower end of the lever 252 straddles the arm 197 of the motor release lever 194. Whenever this arm 197 is moved to the right, as viewed in Fig. 6, it rocks the lever 252 counter-clockwise, thus moving the slide 250 to the left, whereupon the stud 180 of the depressed key 161, 162, or 163 is engaged by the horizontal section of a bayonet slot 254 of the slide 250, thus locking whichever one of the keys 161, 162, or 163 in its depressed position. At the same time, the section of the slide 250 above the horizontal portion of the bayonet slot 254 is moved beneath the studs 180 of whichever one of the keys 161, 162, or 163 is not depressed, thus preventing their depression while another one of those keys is depressed.

This mechanism also functions in connection with the total key 164 through the stud 186, which is locked by the horizontal portion of a bayonet slot 255 in the right end of the slide 250.

When the lever 194 is rocked clockwise, as viewed in Fig. 5, the arm 197 is again moved back into the position shown here, whereupon it rocks the lever 252 clockwise, thus moving the interlocking or locking slide 250 back to the position shown in Fig. 5, wherein any one of the keys 161 to 164 may be depressed, so that the studs 180 and 183 may be moved downwardly into the vertical sections of the bayonet slots 254 and 255, respectively, to release the machine for operation in the manner described previously.

DIFFERENTIAL MECHANISM

The differential mechanism shown in the present application is substantially the same as that shown in the above-mentioned Peters Patents Nos. 1,386,021 and 1,386,022 and the White Patent No. 1,854,875, the White patent showing the subtracting control of the differential mechanism.

There is one differential unit associated with each of the banks of amount keys 120, and, since they are all substantially the same except for minor differences which will be pointed out hereinafter, it is thought sufficient to describe one unit of this differential mechanism, which is shown in side elevation in Fig. 2. However, the complete assemblage of the differential mechanism is shown in Fig. 5 in plan view; that is, there is one unit shown for each of the amount banks of keys 120 which are shown in Fig. 1.

Each of the differential units consists mainly of a differentially adjustable lever carrying an actuating rack for the totalizer pinion associated with that particular denominational order; a differentially adjustable diverging lever for controlling printing mechanism to be described hereinafter; a stop bar pivotally mounted on the diverging lever and adapted to control its movement; a coupling device adapted to couple the differentially adjustable lever and the diverging lever for movement in unison during adding operations; a subtract and control device to control the coupling device whereby the differentially adjustable lever moves one distance and the diverging lever moves a different distance (complementary one to the other to the complement

of ten) during subtract operations; and a positively operated restoring bail which cooperates with the differentially adjustable lever and the diverging lever to restore them to their normal positions to cause the amount set up on the keyboard to be either added to or subtracted from, as the case may be, the totalizer, to be described hereinafter.

Differential mechanism—adding

Pivotally mounted upon a shaft 260 (Figs. 2 and 5) supported by the side frames 30 and 31 is an actuating lever 261. The actuating lever 261 (see also Fig. 4) carries at its upper end the usual totalizer actuating rack 262, a stop plate 263, and a carrying spring 264. The rack 262 has two studs 265, which are free to slide in the usual slots in the actuating lever 261 to provide a relative movement between the lever 261 and the rack 262 when it is necessary to make a carry or transfer in the totalizer, to be described hereinafter.

Projecting forwardly from the lever 261 and integral therewith is an arm 266 having a slot 267, into which projects a pin 268 carried by an arm 269 pivotally mounted on a shaft 270 supported by the side frames 30 and 31.

Pivoted on the shaft 260 adjacent the rack lever 261 is a diverging lever 271 having a rearwardly extending arm 272, which is connected to printer mechanism to be described hereinafter. The diverging lever 271 also has a forwardly extending arm 273 having a slot 274, into which projects the previously described pin 268. This pin 268 normally acts, during adding operations, totaling operations, and sub-totaling operations, to couple the actuating rack lever 261 to the diverging lever 271 so that they will move in unison.

Pivoted on a stud 275, carried by the diverging lever 271, is the usual stop bar 276, which projects forwardly beneath all of the amount keys 120 in its associated bank and is guided near its front end in a slot in the tie plate 39. The stop bar 276 is also in alignment with the zero stop pawl 133, as shown in Fig. 3. The stop bar 276 is provided with the usual stop shoulders 277 to cooperate with the stems of the amount keys 120, so that a spring 278, attached to the stop bar 276, may differentially position the stop bar under control of the depressed key in the bank associated with said bar. When no key in a bank is depressed, then the forward end of the stop bar 276 contacts the zero stop 133, which remains in the position shown in Fig. 3 when no key in its associated bank is depressed.

When the stop bar 276 is moved forwardly or to the left, as shown in Fig. 2, by its spring 278 differentially as determined by the key 120, which is depressed, the diverging lever 271 is rocked counter-clockwise, whereby the arm 272 thereof positions a type bar, to be described hereinafter, so that the amount corresponding to the key depressed may be printed. This differential movement of the diverging lever 271 is transmitted through its arm 273, the coupling pin 268, and the arm 266 to the differentially adjustable actuating lever 261, so that the actuating rack 262 may be adjusted to the left, as viewed in Fig. 2, differentially an amount determined by the value of the key 120, which has been depressed.

Normally the actuating lever 261 and the diverging lever 271 are held in the positions shown by a restoring bar 281, which is secured to an arm 282 (Fig. 2) and an arm 283 (Fig. 18), both

of which are secured to the shaft 260. The arm 283 has an integral arm 284, to which is pivoted a driving pitman 285, the rear or right end of which, as viewed in Fig. 18, is slotted to surround a collar on the shaft 76. This pitman 285 carries a roller 286, held by a spring 288 in contact with a cam 287 secured to the drive shaft 76. The spring 288 is connected to the arm 284 and to a hook (not shown) connected to the shaft 76.

As has been previously described, it will be recalled that the shaft 76 receives first a counter-clockwise movement and then a clockwise movement to its normal position. During the counter-clockwise movement of the shaft 76, the cam 287 is moved likewise, and the spring 288 causes the roller 286 to follow a surface 289 of the cam 287, thus rocking the arms 283 and 282 counter-clockwise to move the bail 281 to the left, as viewed in Fig. 2, whereupon the spring 278 may move the diverging lever 271 and the actuating lever 261 counter-clockwise different distances, depending upon the value of the key 120 depressed in that particular bank.

To insure that the arms 282 and 283 get their full counter-clockwise movement, the pitman 285 has a roller 290, which is contacted by a surface 291 of the cam 287 should the spring 288 fail to rock the arms 283 and 282 their fullest extent counter-clockwise.

The timing of the rocking of these arms 282 and 283 is so arranged that it occurs immediately after the totalizer, to be described hereinafter, is disengaged from the actuating racks 262.

As the drive shaft 76 is restored clockwise to its normal position, the cam 287, through the pitman 285, rocks the arms 282 and 283 clockwise to their normal positions, as shown in Figs. 2 and 18, whereupon the bail 281 positively restores to normal position any and all of the diverging levers 271 and actuating levers 261 which have been differentially positioned under control of depressed keys in their associated banks.

The bail 281 carries the usual alining bar 292, having the usual alining notches (not shown herein but shown in the above-mentioned Peters Patent No. 1,386,021).

In the machine shown embodying the present invention, as illustrated in Fig. 1, there are eight banks of amount keys, and therefore there are eight complete sets of differential units, each unit including the differentially adjustable rack lever 261 and its rack 262 and transfer mechanism, the differentially adjustable diverging lever 271, and the stop bar 276.

Therefore, from the above description it can be clearly seen that, when the rack levers 261, their racks 262, and the diverging lever 271 are rotated counter-clockwise different distances, depending upon the value of the keys 120 depressed in the rows associated with the particular differential unit, the printing bars, to be described hereinafter, will be differentially positioned by the arms 272, after which the printing hammers, to be described hereinafter, are released to cause the amount so set up by the arms 272 to be printed upon the tape around the platen of the printing mechanism.

Now, when the restoring bail 281 is moved clockwise back to its normal position by the pitman 285 (Fig. 18), the rear edge of said bail contacts all of the differentially adjustable rack levers 261 that have been moved out of their normal positions under control of depressed keys, and also contacts the edges of the diverging

levers 271, which have been likewise differentially moved, and restores them to their normal positions. The arms 272 of the diverging levers restore the printing bars to their normal positions, and, during the clockwise movement of the rack levers 261 to normal position, the racks 262 add into their associated totalizer wheels the amounts corresponding to the values of the keys which have been depressed.

10

TOTALIZER

The totalizer in the machine embodying the present invention is substantially the same as that shown in the above-mentioned Peters and White patents, and therefore it has not been thought necessary to go into a full detailed description or illustration of the same in this application. For a full description of the totalizer and the carry or transfer mechanism associated therewith, reference may be had to the above-mentioned Peters and White patents.

In the present invention, the totalizer includes a totalizer wheel 300 for each of the denominational orders of amount keys 120. This wheel 300 is turnably mounted on a totalizer shaft 301. Secured to each of the totalizer wheels 300 is a pinion 302 normally in mesh with its associated actuating rack 262, as shown in Fig. 2.

The totalizer wheels 300, the pinion 302, and the shaft 301 are supported by a frame consisting of a pair of arms 303 and 304 (Figs. 2, 5, and 15) connected together at their front ends by a rod 305 pivotally mounted on the trunnions 127 (Fig. 2) and 128 (Fig. 8), which have been described previously. To make the totalizer frame more rigid, there is another connecting rod 306, which is secured to the pair of arms 303 and 304.

This frame, consisting of the arms 303 and 304 and the rods 305 and 306, is mounted for rocking movement on the trunnions 127 and 128 by means to be described hereinafter. Normally it is in such a position that the pinions 302 are in engagement with the racks 262, as shown in Fig. 2. The reading characters on the totalizer wheels 300 are visible through an opening in a plate 307, which is carried by the arms 303 and 304 so as to rock with the totalizer frame.

The usual aliner 308 is rigidly mounted on rods 309 and 310, carried by the machine side frames 30 and 31, and is in such a position that, when the frame arms 303 and 304 are rocked to disengage the pinions 302 from the racks 262, said pinions will automatically engage the aliner 308, there being one for each denominational order 55 of the totalizer, to properly aline the pinions and totalizer wheels 300 while they are disengaged from the actuating racks 262.

The direction of addition in the totalizer shown herein is in a counter-clockwise direction, 60 as will be readily observed from the previous description of the differential mechanism.

In other words, when the differential rack 262 is moved to the left under the control of its spring 278, the totalizer pinions 302 at that time 65 are disengaged from the racks 262. After the racks have been set, the pinions 302 are again engaged therewith, and the restoring bail 281 restores the racks 262 through their supporting levers 261, thus causing the amount to be positively added into the totalizer wheels 300. It is thought that the above description of the totalizer will be sufficient in view of the illustration and description in the Peters and White patents 70 above mentioned.

Transfer or carry mechanism

Whenever one of the totalizer wheels 300 passes through zero, a carry or transfer mechanism is put into effect, which is fully illustrated and described in the above-mentioned Peters patent, so that the wheel 300 of next higher denominational order will be advanced one step. The transfer mechanism will be briefly described. The stop plate 263 is secured to the rack 262 and normally contacts a lip 311 of a transfer lever 312, as shown in Figs. 2 and 4.

This transfer lever 312 has a bail 313, by means of which said lever 312 is pivoted on a rod 314 carried by the several aliners 308. A spring 315, connected to the lever 312 and to a latch 316, holds the lever 312 up against a flange 317 on the latch 316. This latch 316 has a bail 318, by means of which said latch is pivoted on a rod 319 carried by the aliners 308.

The forward end of the transfer lever 312 has a flange 320 in the path of movement of a transfer cam 321 secured to the left side of the totalizer wheel 300.

When the totalizer wheel 300 passes from 9 to 0, its transfer cam 321, as it is turning counter-clockwise (Fig. 4), contacts the flange 320 and rocks the lever 312 counter-clockwise, thus lowering the lip 311 out of the path of the plate 263, and, at the same time, the spring 315 rocks the latch 316 counter-clockwise, whereupon the flange 317 is moved above a shoulder 322 of the lever 312 to latch the lever in its tripped position. As the lip 311 is lowered, the spring 264 moves the actuating rack 262, associated with the wheel 300 of next higher order, one step to turn in a transfer or carry. This one step of movement of the rack 262 is controlled by contact of the end of the plate 263 with a shoulder 323 formed up on the lip 311.

As will be described hereinafter, the totalizer is disengaged from the racks 262 at the very beginning of the machine operation by rocking the frame 303-304 counter-clockwise. When this occurs, all tripped latches 316 are restored to normal positions by the rear ends of partition plates 324, which are in line with and contact a finger 325 on each of the tripped latches 316, and rock said latches clockwise. When the totalizer is disengaged from the racks 262, they are immediately moved forwardly, as described above, whereupon the stop plates 263 are moved from above the lips 311. Therefore the springs 315, being tensioned by the restoring of the tripped latches 316, rock the tripped transfer levers 312 clockwise to normal to position the shoulders 322 behind the flanges 317 of the latches 316 and also to position the lips 311 directly behind the stop plates 263.

The racks 262 are now in proper positions either to add into or to subtract from the totalizer wheels 300 any amount set up on the keyboard.

SUBTRACTING MECHANISM

In the present machine, subtraction from the totalizer wheels 300 is caused by complementary addition in substantially the same manner as that shown in the above-mentioned White Patent No. 1,854,875.

The subtracting mechanism does not in any way change any of the transfer mechanism associated with the totalizer, nor does it require additional transfer mechanism, because, as above mentioned, subtracting is effected by complementary addition, and therefore the totalizer wheels

300 turn in the same direction for subtracting a number therefrom as they do for adding a number thereto. The entire control for subtracting is through the differential mechanism, and this control will now be described. Since the subtracting devices for each differential are substantially the same, the subtracting device for one differential unit will be described in detail.

Secured to each of the stop bars 276 (Fig. 2) is 10 a bar 331 having a gooseneck 332 carrying a pin 333, which projects beneath the stop bar 276, as clearly shown in Fig. 5. Secured to each of the arms 269 by a sleeve or hub connection is a subtract stop arm 334 adapted to cooperate with the 15 pin 333 in a manner to be described hereinafter. A spring 335 connects the subtract stop arm 334 with its associated diverging lever 271.

As shown in Fig. 5, the stop arm 334 is normally out of the path of the pin 333, and consequently, 20 when the arm 269 and is associated stop arm 334 are rocked clockwise in adding operations, as has been previously described, the arm 334 passes by the pin 333 when this arm 334 is rocked different distances under control of the stop bar 276. 25 During adding operations, this is merely an idle movement of the stop arm 334.

However, during subtraction operations, this arm 334 is moved to the right (Fig. 5) by means to be described hereinafter, to put it in the path 30 of travel of the pin 333. In other words, all of the arms 334, their associated arms 269, and the shaft 270 are moved to the right. This movement of the arms 269 disengages their studs 268 from the arms 273 of the diverging levers 271.

The arm 334 associated with the units order is normally set to the complement of ten with respect to the pin 333, whereby displacement of the rack lever 261 will always be to the tens complement of zero or the tens complement of any number set up by the units keys 120. All the 40 rest of the stop arms 334 are normally set to the complement of nine with respect to the pins 333 in their associated denominational orders, whereby displacement of their associated rack levers 261 will be to the nines complement of zero or the nines complement of any number set up by the associated bank of keys 120. This simply means that, when nothing is subtracted from the units order, ten will be added thereto and cause a transfer or carry into the next higher denominational order, with the following result: If 30 is subtracted from zero, 10 will be added into the units order, and 6 or the nines complement of 3 will be added in the tens order, so that the tens totalizer wheel will show not 6 but 7, due to a carry from the units order over into the tens order. Each of the higher denominational wheels will show 9, because all of the arms 334 above the units order cause their rack levers 261 to be displaced nine steps when nothing is subtracted, and therefore 9 will be added to these wheels 300, thus showing the tens complement of the number on the totalizer wheels 300. In other words, when 30 is subtracted from nothing, the totalizer will show 99999970, which represents the tens complement of 30.

Assuming that the denominational order in Fig. 2 is other than the units order, to subtract 3 from this denominational unit, the operator depresses the "3" key 120 and then depresses the 50 subtract key 162, which, by means to be described hereinafter, will cause the shaft 270 and the arm 334 to be moved so that the arm 334 will be in the path of the pin 333. Now, when 55 the ball 281 is moved to the left in the manner

previously described, the stop bar 276 will move to the left and the diverging lever 271 will be moved with it a distance of three steps, under control of the "3" key, which has been depressed, because this key will control the stopping of the stop bar 276 and consequently of the diverging lever 271, whereupon the type bar will be set to have "3" printed therefrom. However, since the coupling pin 268 has been disengaged from the slot 274 in the diverging lever arm 273, the arm 269 and the stop arm 334 will be rocked in a clockwise direction under the influence of a spring 335, connected to the arm 334 and the diverging lever 271, until the stop arm 334 contacts the pin 333, which in this particular instance is six steps of movement, or the nines complement of 3. Since the coupling pin 268 is still in engagement with the slot 261 of the arm 266 on the rack lever 261, said rack lever will be rocked counter-clockwise six steps under the control of the pin 333 and arm 334 associated with the stop bar 276, which has been set three steps under control of the "3" key 120.

Now, when the restoring bail 281 is restored to its normal position in the manner previously described, it can be clearly seen that 6 will be added into the totalizer wheel 300 associated with this particular denominational unit. Near the end of this operation, the shaft 270 and the arms 269 and 334 are moved to the left to their normal positions.

The mechanism for shifting the shaft 270 and the arms 334 and 269 from the position shown in Fig. 5 to the right, so as to disengage the coupling pin 268 from the diverging lever arm 273, and at the same time move the stop arm 334 into the path of the subtract control pin 333, will now be described. To shift the shaft 270, it is necessary to rock it clockwise, and this rocking of the shaft 270 is also under the control of the subtract key 162.

Pivoted mounted upon the shaft 270 (Figs. 5 and 8) is a bell crank 340 carrying a roller 341 cooperating with a finger 342 of a lever 343 pivoted upon a screw stud 344 secured to the right side frame 31. The lever 343 carries a roller 345 normally resting in a notch 346 of the drive plate 103. During each operation of the machine, whether it be an add operation or a subtract operation, the operating plate 103 rocks the lever 343 clockwise, causing the roller 345 to ride on a surface 347 of the drive plate 103, with the result that the finger 342, through the roller 341, rocks the bell crank 340 clockwise. A spring 348 maintains the roller 341 against the finger 342. When the drive plate 103 returns to its normal position, so that the roller 345 is opposite the notch 346, the spring 348 rocks the bell crank 340 counter-clockwise, thus rocking the lever 343 counter-clockwise to position the roller 345 back into the notch 346.

This bell crank 340 carries a stud 350, upon which is pivoted a latch 351, having a finger 352 held against a stud 353 of a lever 354, pivoted on the stud 142, by a spring 355 connected to a pin on the bell crank 340 and a flange 356 on the latch 351. A spring 357 holds a roller 358 on the lever 354 normally in the position shown in Fig. 8 in contact with the under side of a finger 359 on the subtract key stem 167. Secured to the shaft 270 is an arm 360 having a shoulder 361 adapted to cooperate with the flange 356 of the latch 351.

When it is desired to subtract the number set up on the keyboard, the operator depresses the subtract key 162, whereupon the finger 359 there-

of, by its contact with the roller 358, rocks the lever 354 clockwise, thus removing the pin 353 from the finger 352 of the latch 351, whereupon the spring 355 rocks the latch 351 counter-clockwise, moving the flange 356 beneath the shoulder 361 of the arm 360. Consequently, when the bell crank 340 is rocked clockwise by the drive plate 103 in a manner previously described, the arm 360 and the shaft 270 will likewise receive this clockwise movement.

When the arm 360 is coupled to the bell crank 340 in the manner just described, to rock the shaft 270, an arm 362 (Fig. 11), secured to the left end of the shaft 270, also receives this clockwise movement. This arm 362 carries a roller 363 engaging a cam slot 364 (Fig. 5) in a bracket 365 secured to the left side frame 30. This cam slot 364 is of such a shape that, when the arm 362 is rocked clockwise, the cam slot 364 will cause the shaft 270 and all the parts thereon to be shifted to the right, as viewed in Fig. 5, for the purpose of bringing the stop arms 334 in the paths of movement of the pins 333 and for the purpose of uncoupling the rack levers 261 from the diverging levers 271.

Whenever the arm 360 is coupled to the bell crank 340 by the subtract latch 351, there is provided a means to restore these parts to their normal positions at the end of the subtract operation of the machine. This means includes a stud 366 (Fig. 8) carried by the arm 360, which is engaged by a lever 367 pivoted on the screw stud 344. This lever 367 is held against the stud 366 by a spring 368 and has a roller 369 normally resting in a notch 370 in the drive plate 103.

When the drive plate 103 is rocked counter-clockwise, a surface 371 between the notches 370 and 346 is such as to permit the stud 366 to rock the lever 367 counter-clockwise, while the arm 360 is being rotated clockwise by the latch 351. The surface 371 being nearer the center 100 than is the surface 371, the lever 367 can be rocked still farther counter-clockwise as the arm 360 continues its full clockwise movement. Near the end of the operation, when the drive plate 103 is restored to normal position, the cam surface 371 rocks the lever 367 clockwise, whereupon it, through the stud 366, positively rocks the arm 360 counter-clockwise to its normal position. Assisting this movement is a spring 372 (Fig. 11) connected to an arm 373, which is fast on the left end of the shaft 270. This arm 373 carries a stop plate 374 adapted to strike a rubber bumper 375 carried by a bracket 376 on the side frame 30. This rubber bumper 375 absorbs the shock of the subtracting mechanism when it is restored to its home position, and at the same time reduces the noise.

From the above description it will be very clear that, whenever the subtract key 162 is depressed to subtract an amount set up on the amount keys 120, the latch 351 is released so as to couple the arm 360 to the driven bell crank 340 to cause the subtract stop arms 334 to control the differential mechanism whereby the amount on the keyboard will be subtracted from the totalizer by a process of complementary addition.

TOTALIZER ENGAGING MECHANISM

As has been previously stated, the totalizer pinions 302 are normally in engagement with the actuating racks 262, as shown in Fig. 2.

During adding operations, the first thing that happens is that the totalizer is disengaged from the actuators, the actuators are differentially

positioned, the totalizer is then engaged therewith, and the actuators are positively restored to their normal positions to add into the totalizer the amount corresponding to the value of the keys depressed.

However, as has been mentioned above, when subtracting, the complementary amount is added into the totalizer under control of the mechanism described under the heading of "Subtracting mechanism."

During total-taking operations, the machine is put through two machine cycles, the first cycle being for the purpose of restoring any tripped transfer devices that might have been tripped during the preceding operation of the machine, and then, during the second cycle, the totalizer is left engaged with the actuating racks while the racks are moved counter-clockwise, as viewed in Fig. 2, so that the amount that was on the totalizer will be taken therefrom in the manner described in the above-mentioned Peters Patent No. 1,386,021, and the totalizer is then disengaged while the actuators are restored to their normal positions, thus leaving the totalizer at zero at the end of the operation.

During sub-total-taking operations, the machine is also put through two machine cycles, the first of which restores any tripped transfer devices to normal, but during the second cycle the totalizer is left engaged with the actuating racks when they are moved to their left, so that the amount that was on the totalizer may be printed, after which the totalizer is held engaged with the racks while the racks are restored to their normal positions, thus putting back into the totalizer the amount that was taken therefrom. The means for accomplishing the above results will be described under the various headings.

First will be described the general totalizer engaging and disengaging mechanism. Referring particularly to Figs. 15 and 18, the arm 304 of the totalizer frame has an integral arm 385 carrying a roller 386, which projects into a cam slot 387 of a totalizer engaging lever 388 pivotally mounted on a stud 389 supported by the right side frame 31. Pivoted on the stud 389 adjacent the totalizer engaging lever 388 is a lever 390 having a pin 391 contacting a surface 392 of an arm 393 of the lever 388.

The upper end of the lever 390 carries a stud 394, upon which is pivoted a coupling pawl 395 held in engagement with a stud 396 on the arm 393 by a spring 397.

The lower end of the lever 390 has a stud 398 engaged by a notched pitman 399, which in turn is pivoted to the upper end of a bell crank 400 pivoted on a stud 401 mounted in the right side frame 31.

The pitman 399 is held in engagement with the stud 398 against the action of a spring 402, by arm 403 of a bell crank 404 pivoted on a stud 405 carried by the side frame 31. A spring 406 holds the arm 403 in contact with a stud 407 of an arm 408 integral with the pitman 399.

The bell crank 400 also carries a stud 409, which cooperates with a shoulder 410 of a toggle link 411 pivoted at 412 to a toggle arm 413 secured to the rear drive shaft 76. This toggle arm 413 is also connected by a stud 414 to the previously mentioned drive plate 101 (Fig. 8) and has a spring 415 connected thereto, which holds the link 411 against the stud 409.

It will be recalled that the shaft 76 receives first a counter-clockwise movement and then a clockwise movement to its normal position.

When the shaft is moved counter-clockwise, the toggle arm 413 moves likewise, carrying with it the toggle link 411, until the shoulder 410 contacts the stud 409 and rocks the bell crank 400 counter-clockwise until the center of the pivot 412 passes to the left of a line from the center of the stud 409 to the center of the shaft 76. The counter-clockwise movement of the bell crank 400 moves the pitman 399 to the left and rocks the lever 390 clockwise, whereupon the pin 391, through its engagement with the arm 393, rocks the arm 385 and engaging lever 388 clockwise, and the cam slot 387, through the roller 386, rocks the totalizer frame 303-304 counter-clockwise to disengage the totalizer pinions 302 from the actuator racks 262.

After this disengagement of the totalizer from the racks 262, the racks are differentially positioned in the manner described previously.

20 After they have been so positioned, and prior to their restoration to normal positions, the left side of the toggle link 411, as viewed in Fig. 15, strikes a stud 416 carried by an arm 417 integral with the bell crank 400.

25 This occurs as the toggle arm 413 nears the end of its counter-clockwise movement. As it about reaches the end of its counter-clockwise movement, a shoulder 418 of the toggle link 411 is positioned beneath the stud 416 by the spring 30 415, after which the clockwise movement of the toggle arm 413 to its normal position begins, whereupon the shoulder 418, by its contact with the stud 416, rocks the arm 417 and consequently the bell crank 400 clockwise, thus moving the pitman 399 to the right, which rocks the lever 390 counter-clockwise to its normal position, whereupon the coupling pawl 395, through its engagement with the pin 396, rocks the engaging lever 388 counter-clockwise to its normal position, and the cam slot 387 rocks the totalizer frame 303-304 clockwise to again engage the totalizer pinions 302 with the actuator racks 262. After this engagement, the racks 262 are restored to their normal positions in a clockwise direction (Fig. 2) by the restoring bail 281 in a manner previously described, whereupon the amount which was set upon the keyboard is entered into the totalizer.

To positively insure that the engaging and disengaging lever 388 is restored counter-clockwise to its full normal position, this lever carries a stud 419, which is normally in the position shown in Fig. 15. At the beginning of the counter-clockwise movement of the shaft 76, it will be recalled, the main drive shaft 100 is rocked counter-clockwise, whereupon an arm 420, secured to the main drive shaft 100, is moved counter-clockwise away from the stud 419 to allow the lever 388 to be rocked clockwise in the manner previously described. As the shaft 100 is restored clockwise to its normal position, the arm 420 contacts the stud 419 if the coupling pawl 395 should fail to rock the lever 388 counter-clockwise to its full normal position, and positively restores said lever 388 to its normal position.

As viewed in Fig. 15, it can be seen that this arm 420 is just contacting the stud 419 in the normal positions of the parts, and therefore, if the coupling pawl 395 fully restores the lever 388 counter-clockwise, then the arm 420 has no work to do during adding operations except to hold the lever 388 in its normal position once it is restored to that position by the coupling pawl 395.

To assist in maintaining the totalizer engaging and disengaging lever 388, and consequently the totalizer, in their various positions of adjustment, the lever 388 carries a stud 431, upon which is pivoted an alining pawl 432 having notches 433 and 434 cooperating with a stud 435 carried by the side frame 31. A spring 436 normally holds the notch 433 in engagement with the stud 435 when the totalizer is in engagement with the actuators. When the lever 388 is rocked clockwise to disengage the totalizer from the actuators in the manner described above, the notch 433 is cammed off of the stud 435, and the notch 434 engages the stud to hold the totalizer in its disengaged position while the actuator racks 262 are being differentially adjusted prior to adding.

When the lever 388 is moved counter-clockwise to its normal position, the pawl 432 is pulled to the right, as viewed in Fig. 15, into the position shown, wherein the notch 433 again engages the stud 435.

There is also an alining device associated with the arm 417 and the bell crank 400. The arm 417 has notches 437 and 438, and, in the normal positions of the parts, as shown in Fig. 15, a stud 439, carried by an arm 440 pivoted on a stud 441 carried by the side frame 31, is held in engagement with the notch 437 by a torsion spring 442, to hold the bell crank 400 and the arm 417 in their normal positions. When the bell crank 400 and the arm 417 are rocked counter-clockwise, the arm 440 is rocked so that the stud 439 will bob from the notch 437 into the upper notch 438 to hold the bell crank 400 and the arm 417 in their moved position, which is the position in which the totalizer is disengaged from the actuators, and will retain it in that position until the shoulder 418 of the toggle link 411 contacts the stud 416 of the arm 417 and rocks said arm clockwise back to its normal position, at which time the stud 439 will again be engaged with the alining notch 437 of said arm. From the above description it will be very clear how the totalizer is moved into engagement with and disengaged from the actuator racks 262 for the purpose of adding.

When subtracting, the totalizer is disengaged from and engaged with the actuator racks 262 in exactly the same manner and by exactly the same means as has just been described for adding operations.

For total-taking operations—that is, for taking the total from the totalizer and leaving it clear at the end of the operation of the machine—there is provided special mechanism for controlling the time of the engaging and disengaging of the totalizer by the engaging lever 388, under control of the total key 164.

Totalizing control of totalizer engaging mechanism

For a total-taking operation, it is necessary, as above mentioned, that the machine be put through two machine cycles, the first of which is to restore to normal any tripped transfer devices which may have been tripped during the last preceding adding or subtracting operation. This first machine cycle is often referred to as an idle cycle.

In many machines on the market, this first cycle is made by operating the so-called touch bar, or motor release bar, wherein the machine goes through an idle operation, after which it is necessary for the operator to then depress the total key to make a total.

However, in the present invention, all that it is necessary for the operator to do is to depress the total key 164, and the machine will automatically perform a two machine cycle operation.

Depression of the total key 164 releases the machine, and the totalizer, being normally in engagement with the actuator racks 262, as has been previously described, is first disengaged from the racks 262 on the regular adding time and is then later engaged with the racks 262 on adding time. All of this happens during the first machine cycle of the operation, during which time any of the previously tripped transfer devices are restored to their normal positions during the very first part of this operation.

During this first machine cycle, the actuating levers 261 and the diverging levers 271 are prevented from being moved in a counter-clockwise direction beyond the zero position due to the fact that the zero stops 133 (Fig. 3) are retained in their normal positions, thus preventing any indexing movement of the stop bars 276 and consequently of the actuating levers 261 and the diverging levers 271.

It is during this first machine cycle of the operation that the automatic means comes into effect for automatically releasing the machine for the second cycle of the operation, which will be a totalizing cycle to clear the totalizer and print the amount taken therefrom. It might be stated here that, near the end of the first or idle cycle, the total key 164 is released and restored to its normal position, and this is the reason for the automatic releasing of the machine for the second or clearing cycle of the total-taking operation. Otherwise it would be necessary to depress the total key 164 again. The means for releasing the machine for operation upon depression of the total key 164 will now be described.

It will be recalled that, to release the machine for operation, it is necessary to rock the lever 199 clockwise to allow the counter-clockwise movement of the arm 197 (Fig. 5) under the action of its spring 196, all of which has been fully described in the early part of this application.

When the total key 164 is depressed, its stud 223 contacts and rocks the lever 220 clockwise, which in turn rocks the lever 221 counter-clockwise, whereupon its finger 215, through the stud 211, rocks the lever 199 clockwise to release the arm 197 for movement toward the right (Fig. 6) to close the motor switch in the manner previously described.

During this operation, as above mentioned, since none of the keys 120 are depressed, the zero stops 133 are permitted to remain in their normal positions, so that, after the totalizer is disengaged from the racks 262, the springs 278 on the stop bars cannot move the stop bars 276 forwardly beyond their zero-positions, as they do during adding operations.

During this first cycle, the pitman 399 (Fig. 15) is moved first to the left and then to the right, in the manner previously described, by the toggle link 411 and the toggle arm 413 to first disengage the totalizer from the actuator racks and then engage it with the actuator racks.

Also, during this first machine cycle of the total-taking operation, the following mechanism comes into play or operation, so that the machine will be automatically released for the second machine cycle of a total-taking operation, during which second machine cycle, and as above stated,

the totalizer is cleared and the amount taken therefrom is printed.

By means to be described hereinafter, the bell crank 404 (Fig. 15) is rocked counter-clockwise near the end of the first machine cycle. Pivoted to the bell crank 404 is a link 443 having a stud 444 engaged by a forked arm 445 pivoted on a stud 446 carried by the side frame 31. The arm 445 has a pin 447 (Figs. 9 and 16) adapted to cooperate with a shoulder 448 of an arm 449 also pivoted on the stud 446. The arm 445 has a finger 450 and the arm 449 has a finger 451 cooperating with a flange 452 of a latch lever 453 pivoted on a screw stud 454 carried by the right side plate 124 of the keyboard. A spring 455 holds the flange 452 normally in the position shown in Figs. 15 and 16.

This latch lever 453 has pivoted thereon, at 456, a by-pass pawl 457 normally held, by a spring 459, against a bent-over finger 458 on the lever 453. By-pass pawl 457 has a flange 460 normally in the path of the previously described stud 144 on the drive plate 103. When this plate 103 is rocked counter-clockwise, as previously described, the stud 144 strikes the upper edge of the flange 460 and rocks the by-pass pawl 457 clockwise against the action of its spring 459 without in any way moving the lever 453.

When the bell crank 404 is moved counter-clockwise, as above mentioned, at substantially the end of the first machine cycle, by means to be described hereinafter, it rocks the arm 445 counter-clockwise (Figs. 15 and 16) to move the finger 450 below the flange 452 of the latch lever 453. At the same time, the pin 447 rocks the arm 449 to move its finger 451 also below the flange 452. When both fingers 450 and 451 are below the flange 452, the spring 455 rocks the latch lever 453 counter-clockwise, thus latching the arms 445 and 449 in their moved positions at the end of the first machine cycle.

When the total key 164 was depressed, it will be recalled, the lever 199 was rocked clockwise, thus lowering the lug 198 below the path of movement of the arm 197, and that the arm 197 was then immediately moved to the right (Fig. 15) on top of the lug 198. The counter-clockwise movement of the latch lever 453, described above, causes an arm 461, integral therewith, to move down on top of the flange 203 on the lever 199, and hold the lever 199 in the moved or motor-releasing position at the end of the first machine cycle, and consequently the arm 197, after being restored near the end of the first machine cycle, is immediately moved back to the right over the lug 198, to cause the motor to be released for an immediate second machine cycle of a total-taking operation. Therefore, even though the total key 164 is released by the lever 252 (Fig. 6) when the arm 197 is moved to the left (Fig. 15), in the manner described previously, the immediate movement of the arm 197 to the right locks the total key 164, by the lever 252 and the bar 250, but, as stated above, the motor is released to cause the second machine cycle.

During this second machine cycle of the total-taking operation, as the stud 144 is moved down, it again by-passes the pawl 457, but, upon the return upward movement of the stud 144, it, through its contact with the flange 460, rocks the lever 453 clockwise to its normal position, after which the bell crank 404 is released, by means to be described hereinafter, to be returned to its normal position by the spring 406, whereupon the finger 451 holds the latch lever 453 in the position shown

in Figs. 15 and 16. At the same time, the arm 449 is restored to its Fig. 16 position by means of a stud 462 on the arm 449, which is contacted by the upper edge of the arm 445 while this arm is being returned to its original position.

The means for rocking the bell crank 404 counter-clockwise will now be described. Pivoted on a rod 470 (Figs. 7 and 15), which rod is supported by the side frames 30 and 31, is a plate 471 rigidly connected by a stud 472 to a lever 473 also pivoted on the rod 470. A screw 474 holds the lever 473 in position on the rod 470. Pivoted on a stud 469 on the plate 471 is a link 475, also pivoted to the bell crank 404. When plate 471 is rocked clockwise (Fig. 15) in a total-taking operation in a manner to be described later herein, the stud 469 thereon will move in an arcuate path about the rod 470 and will cause the link 475 to be given an upward movement, which rocks the bell crank 404 counter-clockwise. As the link 475 is given its upward movement, its upper end will move to the left from the position shown in Fig. 15.

The lever 473 carries a stud 476, adapted to be engaged by a shoulder 477 (Figs. 6, 8 and 14) of an arm 478 freely pivoted on a stud 479 carried by an arm 480, which in turn is pivoted on a stud 481 carried by the side frame 31. This arm 480 has a spring 482 attached thereto, which normally holds a surface 483 of the arm against a roller 484 carried by the previously described operating link 102.

Also pivotally mounted on the stud 479 adjacent the arm 478 is another arm 485 having a pin 486, to which is connected a spring 487 also connected to a stud on the arm 478. The pin 486 projects through a clearance slot 488 of the arm 478. The spring 487 acts as a centralizing spring; that is, it holds the arm 478 in the position shown in Figs. 6, 8, and 14, when the machine is at rest, and also acts as a restoring spring to bring the arm 478 into this position after it has been moved either clockwise or counter-clockwise by means to be described hereinafter.

The arm 485 has a slot 489, into which projects a pin 490 on a bell crank 491 pivotally mounted on the rod 470 adjacent the lever 473. A spring 492 holds a pin 493 on the bell crank 491 against a finger 494 of an arm 495 pivoted on a stud 496 supported by the right side frame 31. This arm 495 carries a roller 497 adapted to be contacted by a finger 498 of the total key stem 169 (Fig. 6).

When the total key 164 is depressed, the finger 490 rocks the arm 495 counter-clockwise (Figs. 6 and 8), whereupon the finger 494 rocks the bell crank 491 (Fig. 14) clockwise. This movement of the bell crank 491, through the pin 490 and the slot 489, rocks the arm 485 counter-clockwise, whereupon the spring 487 rocks the arm 478 counter-clockwise until a surface 499 thereof contacts the stud 476 in the lever 473.

Now, when the link 102 (Figs. 8 and 14) is moved to the left, the spring 482 rocks the arm 480 clockwise, which draws the arm 478 to the left until the shoulder 477 passes the stud 476, whereupon the spring 487, still under tension, rocks the arm 478 farther counter-clockwise until the shoulder 477 completely engages the stud 476 on the lever 473.

Now, as the link 102 is moved to the right to its normal position, the roller 484 on the link first contacts a finger 500 on the arm 480 and rocks the arm counter-clockwise until the finger 500 is out of range from the roller, after which 75 the roller, by its contact with the surface 483 of

the arm, completes the counter-clockwise movement of the arm 480 to its normal position. During this return to normal of the arm 480, the shoulder 477, being in engagement with the stud 476, rocks the lever 473 clockwise, which, through the stud 472, rocks the plate 471 (Fig. 15) clockwise, whereupon the link 475 is raised to rock the bell crank 404 counter-clockwise to move the link 443 to the right to rock the arms 445 and 449 counter-clockwise to position their fingers 450 and 451 below the flange 452 of the latch lever 453 in the manner and for the purpose previously described.

The movement of the lever 473, the plate 471, and the bell crank 404, just described, takes place near the end of the first machine cycle of the total-taking operation. During the first part of this cycle of the total-taking operation, the toggle link 411 and the toggle arm 413 (Fig. 15) have moved the pitman 399 to the left and disengaged the totalizer pinions 302 from the actuator racks 262 in the manner previously described.

Since, during this first part of the first machine cycle of operation, the bell crank 404 has not yet been moved, the toggle link 411 and the toggle arm 413 have returned the pitman 399 to its normal position, it having been held in engagement with the stud 398 by the arm 403 of the bell crank 404, and, during such return of the pitman 399, the totalizer pinions 302 were again engaged with the actuator racks 262. However, during the latter part of this first machine cycle, the counter-clockwise movement of the bell crank 404 moves its arm 403 away from the stud 407 in the arm 408 of the pitman 399, and the spring 402 rocks the pitman clockwise around its pivot point on the bell crank 400, so that, when the pitman is moved to the left during the first part of the second machine cycle of the total-taking operation, said pitman, being disengaged from the stud 398, will simply move idly and will not disengage the totalizer pinions 302 from the actuator racks 262, and therefore, when at this time the stop bars 276 are permitted to move to the left to rock the rack levers 261 and the diverging levers 271 counter-clockwise, the racks 262 will clear the totalizers; that is, reversely rotate the wheels 300 until they reach their zero positions. Such zero positions are arrived at when surface 501 of the transfer cam 321 strikes the right side of the flange 320 (Fig. 4) of the transfer lever 312.

The stop bars 276 can move as above mentioned due to the fact that the zero stops 133 (Fig. 3) have been moved away from in front of the stop bars 276 during this part of the second machine cycle. The control of the zero stops 133 during this total-taking operation, consisting of two machine cycles, will be explained hereinafter. While the diverging levers 271 are being rocked counter-clockwise at the time the totalizer is being cleared, the arms 272 of the diverging levers set the type bars, to be described hereinafter, in accordance with the amount which was taken from the totalizer, after which that amount, which in the present case is the total amount, will be printed by means to be described later.

The clockwise movement of the pitman 399 by the spring 402, at the time mentioned above, was not completed due to the fact that, at the time this pitman 399 was moved to the left, a surface 511 of the pitman came into contact with a stud 512 on the restoring bail lever 284 (Fig. 18), which prevented the full clockwise movement of the pitman 399 by the spring 402. Therefore, the first

movement of the pitman 399 to the left during the second machine cycle is an idle movement, as above mentioned.

However, as this lever 284 is moved counter-clockwise shortly after the beginning of the second machine cycle of operation, the stud 512 follows along the surface 511 of the pitman 399 until it passes the end thereof, at which time the spring 402 will rock the pitman 399 farther in a clockwise direction around its pivotal point on the bell crank 400 and cause a notch 513 in said pitman to engage a stud 514 on the lever 390. This occurs after the shoulder 410 (Fig. 15) of the toggle link 411 has left the stud 409 of the bell crank 400 and prior to the time the shoulder 418 has engaged the stud 416. Now, when the shoulder 418 does engage the stud 416 and rock the arm 417 and the bell crank 400 clockwise to normal position during the second machine cycle of the total-taking operation, the pitman 399 is moved to the right, and, due to the fact that the notch 513 at this time is in engagement with the stud 514 of the lever 390, said lever will be rocked clockwise, and its pin 391, by its contact with the arm 393 of the engaging lever 388, will rock the engaging lever 388 clockwise to disengage the totalizer pinions 302 from the racks 262. Therefore, when the restoring bail 281 (Fig. 2) is moved to the right to restore the rack levers 261 to their normal positions, the amount which was taken from the totalizer wheels will not be put back thereon, but the totalizer will be left in its cleared or zero position. Now, near the end of the second machine cycle, and after the racks 262 have been restored, the arm 420 (Fig. 15) strikes the stud 419 on the totalizer engaging lever 388 and rocks the said lever counter-clockwise to its normal position, whereupon its cam slot 387 again engages the totalizer pinions 302 with the racks 262.

By this time, the bell crank 400 has restored the pitman 399 to the right, after which the bell crank 404 is rocked clockwise to its normal position by the spring 406 after the stud 444 has rocked the latch lever 453 counter-clockwise by its cooperation with the flange 460 of the by-pass pawl. Such clockwise movement of the bell crank 404 causes its arm 403 to contact the stud 407 of the pitman 399 and rock the pitman counter-clockwise around its pivot point on the bell crank 400 to again engage said pitman with the stud 398 (Fig. 18) of the lever 390, which is the normal position of the parts.

It will be recalled that, near the end of the first machine cycle, the shoulder 477 (Figs. 8 and 14) of the arm 478 rocks the lever 473 clockwise as the roller 484 rocks the arm 480 counter-clockwise near the end of the first machine cycle. At the beginning of the second machine cycle, the roller 484 is again moved away from the arm 480, and the spring 482 rocks the arm 480 clockwise, whereupon a finger 515 thereon contacts a flange 516 of a finger 517 on the interlocking arm 232, thus stopping the arm 480. The flange 516 is, at this time, in position to intercept the finger 515, since the arm 232 has been rocked clockwise, as seen in Fig. 17, due to movement of the zero stops 133 away from normal position. This short clockwise movement of the arm 480 is sufficient to draw the arm 478 to the left, so that the shoulder 477 is released from the stud 476, whereupon the spring 487 again centralizes the arm 478; that is, disengages the shoulder 477 from the stud 476. Therefore, as the link 102 is restored to the right to its normal position during the second

machine cycle of the total-taking operation, the roller 484 restores the arm 480, which moves the arms 478 and 485 back to their normal positions.

To insure that the subtract latch 351 (Fig. 8) does not become latched during total-taking operations or during sub-total-taking operations, later described, a block 543 fastened to the link 443 has a finger 510 (Figs. 5, 8, and 9), which contacts the finger 352 of the latch 351 and rocks the latter slightly clockwise when the link 443 (Fig. 15) is moved by the bell crank 404. Therefore, when the arm 340 is rocked clockwise, the finger 510 having rocked the latch 351 clockwise, said latch cannot engage the shoulder 361 when the finger 352 is moved away from the stud 353 during total and sub-total operations.

Control of zero stops during total-taking operation

During the first machine cycle of the total-taking operation, when the arm 480 is rocked counter-clockwise by the roller 484, as above described, it will be recalled that the arm 480 rocks the lever 473 and the plate 471 (Fig. 15) clockwise, thus rocking the bell crank 404 counter-clockwise. There is means, to be described hereinafter, connected to this bell crank for moving the zero stops 133 out of the path of the stop bars 278. This, as already explained, involves clockwise movement of arm 232, as seen in Fig. 17, and, since this occurs at substantially the same time that the arm 480 is being rocked counter-clockwise, in order to prevent any interference between the finger 517 on arm 232 and the finger 515 on the arm 480, the finger 517 has a beveled surface 518 (Figs. 14 and 17) and the finger 515 has a beveled surface 519 facing the surface 518.

The control of the zero stop pawls 133 during the first machine cycle and during the second machine cycle of a total-taking operation will now be described.

The previously described link 443 (Figs. 15 and 17) has a slot 531, into which projects a stud 532 on a lever 533 (Figs. 8, 15, and 17) pivoted on a stud 534 supported by the right side frame 31. The lever 533 normally contacts the pin 177 in the previously described key release lever 147.

Pivoted to the bell crank 404 (Fig. 15) and lying alongside the link 443 (Figs. 9, 15, and 17) is a link 535 having a notch 536, which engages the stud 532. The link 535 has a finger 537 normally engaged by a bent-over finger 538 of a lever 539 pivoted on a stud 540 on the side frame 31. The parts just described, including the link 443, are held in their normal positions by the spring 406, with the lever 533 against a stop pin 541 on the machine frame 31. The upper end of the lever 539 is in the path of movement of the stud 144 on the drive plate 103.

At about the middle of the first machine cycle of a total-taking operation, and when the stud 144 contacts the lever 539, it raises the forward end of the link 535 and disengages the notch 536 of the link 535 from the stud 532 and then, as the stud 144 returns upwardly, the link 535 will be moved downwardly to again engage the notch 536 with the stud 532 under the influence of a spring 542 mounted on a plate 543 secured to the link 443, the end of which spring overlies the top of the link 535, as is clearly shown in Figs. 9 and 17. This up-and-down movement of the link 535 during the first part of the first machine cycle of the total-taking operation is an idle movement, and, since the key release

lever 147 is not moved by the lever 533 at this time, the zero stop pawls 133 will be left in their normal positions, shown in Fig. 3, which is in front of the stop arms 276; consequently, while the totalizer is being disengaged from the racks 262 and again engaged therewith, the stop bars 276, and consequently the racks 262, cannot move during this part of the first machine cycle of the total-taking operation, beyond their zero positions.

Near the end of the first machine cycle, when the bell crank 404 is rocked counter-clockwise in the manner described above, the link 535, being in engagement with the stud 532, will be moved to the right, along with the link 443, and consequently will rock the bell crank 533 counter-clockwise, which in turn will rock the key release lever 147 clockwise and, through the mechanism previously described, rock the zero

stop levers 133 counter-clockwise, as viewed in Fig. 3, to remove them from in front of the stop bars 276. At the same time, the interlocking arm 232, which is connected to the zero stop bars 134 by means of the flanges 238 (Fig. 13) will be moved clockwise, as viewed in Fig. 17, and thereby block the arm 480 in the first part of the second cycle.

Now, during the first part of the second machine cycle of a total-taking operation, the racks 262 may be moved forwardly until the surfaces 501 of the transfer cams 321 strike the transfer lip 320, which brings the totalizer wheels 300 to their zero positions. At this time, of course, the stop bars 276 are moved forwardly, and the diverging levers 271, through their integral arms 272, will set the type according to the amount that was taken from the totalizer.

It will be recalled that the bell crank 404 and the links 535 and 443 are latched in their moved positions by the latch lever 453 during the first part of the second machine cycle, and, while they are so latched, and near the middle of the second machine cycle, the stud 144, through the lever 539, again raises the link 535 to disengage its notch 536 from the stud 532, at which time the springs 137 on the zero stop bars 133 (Fig. 2) at once restore the zero stops 133 to their normal positions and consequently rock the key release lever 147 counter-clockwise, which rocks the lever 533 clockwise, whereupon the stud 532 at this time moves to the left in the slot 531 in the link 443, which is at this time being held by the latch 453.

This release of the zero stop pawls 133 at this particular time permits them, under the influence of their springs 137, to be engaged with the straight sides of teeth on a so-called anti-slam rack 544, one of which is secured to the side of the front of each of the stop bars 276, as viewed in Figs. 2 and 5. This is to prevent the stop bars 276 and their associated diverging levers 271 and type bars, to be described later, from being suddenly moved under the influence of the springs 278, after the totalizer has been cleared and while the pinions 302 thereof are disengaged from the racks 262. The particular ones of the teeth on the anti-slam racks 544, which are engaged by the zero stop pawls 133, is dependent upon the amount which was upon the totalizer, because the stop bars 276, in order to clear the totalizer, are moved differentially forwardly, or to the left, as viewed in Fig. 2, an amount proportionate to that which is upon their associated wheels, and consequently each zero stop pawl 133 will engage the particular

tooth of the rack 544 adjacent to the one differentially positioned opposite the pawl during such clearing operations. When the stop bars 276 are restored to normal the zero stop pawls 133 ratchet over the anti-slam racks 544.

Now, near the end of the second machine cycle of a total-taking operation, when the bell crank 404 is restored to its normal position in the manner previously described, both links 443 and 535 are moved to the left (Fig. 15), the slot 531 permitting such movement of the link 443, the link 535 riding on top of the stud 532 until the notch 536 is opposite said stud, at which time the spring 542 lowers the front end of the link and the notch 536 again engages the stud 532, so that the parts will be in their normal positions, shown in Fig. 15, at the end of the second machine cycle of the total-taking operation.

Sub-totalizing control of totalizer engaging mechanism

The means for controlling the totalizer engaging and disengaging mechanism, for the purpose of making a sub-total operation, will now be described.

As is well known in the art, the only difference between a total and a sub-total is that, in making a total-taking operation, the totalizer is left clear or at zero at the end of such operation, whereas in a sub-total-taking operation the totalizer is cleared, the amount taken therefrom is printed, and that amount is then put back into the totalizer so that at the end of this sub-total-taking operation the totalizer still has in it the amount which it had at the beginning of this sub-total-taking operation.

The item key 161, which, it will be recalled, is depressed to release the machine to enter items into the totalizer and to print them, may also be used by the operator, when desirable, as a sub-total key, simply by holding down on this key 161 all through the operation in which the last item is entered. The key 161 then releases the machine for an immediate, subsequent sub-total-taking operation. This sub-total-taking operation consists of two machine cycles, the same as the total-taking operation, the difference being in the changing of the timing of the engaging of the totalizer pinions 302 with the racks 262.

During the first machine cycle of the sub-total-taking operation, the totalizer is disengaged from the actuating racks and again engaged with the actuating racks in the same manner and by the same means as during adding operations. However, during the second machine cycle of a sub-total operation, the totalizer is left engaged with the racks 262, the racks are moved forwardly the same as during a total-taking operation, and then, instead of disengaging the totalizer from the racks 262 after the amount has been taken therefrom, the totalizer is caused to remain in engagement with the racks 262, so that, when they are restored to their normal positions during the second machine cycle of the sub-total-taking operation, the amount which was taken from the totalizer is put back into the totalizer by the racks 262. This means that there is a change in the timing of the rocking of the engaging lever 388 (Fig. 15).

Surrounding a pin near the bottom of the item and sub-total key stem 166 is the forked end of a bell crank 551, which is pivoted on a stud 552 carried by the key frame 171. Pivoted to this bell crank 551 is a link 553, which is

connected to a bell crank 554 pivoted on a stud 555 also supported by the key frame 171. A spring 556 is connected to the bell crank 554 and to a slotted link 557, which surrounds a stud 558 on the arm 478. This connection between the bell crank 554 and the arm 478 is a loose or free connection; that is, there is positively no tension on the spring 556 when the parts are in their normal positions (Fig. 6), as can be clearly seen due to the fact that the stud 558 is substantially in the center part of the slot in the link 557.

When the key 161 is depressed to release the machine to enter an item which is set up on the keyboard, the machine goes through the regular adding operations, as has been previously described. Now, by holding the key 161 depressed, it then becomes not an item releasing key but a sub-total releasing key. Due to the fact that the key 161 is held depressed, its finger 210 holds the lever 199 in its moved or clockwise position, so that the arm 197, after being restored at the end of the item-entering operation, will immediately be moved to the right (Fig. 6) by its spring 196 to cause the motor to drive the machine through the first machine cycle of the sub-total-taking operation.

Whenever the key 161 is depressed, the bell crank 551 moves the link 553 to the left, which rocks the bell crank 554 clockwise and rocks the arm 478 (Figs. 6 and 8) clockwise, and a surface 559 of the arm 478 contacts a stud 560 in the lever 473. However, during adding operations, it will be recalled, the operator removes his hand from the key 161 immediately after depressing it, because the mere depression thereof releases the motor for operation, and the key spring 173 raises the key slightly, which is sufficient to partially restore the bell crank 554, thus removing some of the tension of the spring 556, and consequently a shoulder 561 of the arm 478 cannot get low enough to engage the stud 560 when the arm 478 is moved back to the right to its normal position. During this adding operation, the arm 478 merely moves, after it is rocked slightly clockwise by the spring 556 and the link 557, to the left and then back to the right again, and the centralizing spring 487 rocks the arm 478 back to its normal position, so that, as above mentioned, the shoulder 561 cannot engage the stud 560.

This movement of the arm 478 to the left during this adding operation immediately preceding the sub-total operation is caused by the spring-drawn arm 480 when the roller 484 (Fig. 8) is moved away from the arm 480, as previously described. Since the bar 237 is moved to the right (Fig. 13), the arm 232 is rocked clockwise (Fig. 17); thus moving the flange 516 in the path of the finger 515. Consequently, the arm 480 is prevented from moving its full distance under action of its spring 482, and therefore the arm 478 is also moved only a short distance to the left (Fig. 14).

The key 161 is held depressed all through an item operation, when it is desired to take a sub-total immediately thereafter, and is held depressed long enough in the first machine cycle of the sub-total operation for the spring 556 to rock the arm 478 fully in a clockwise direction after it has been moved to the left its full distance by the arm 480 (Fig. 8) in the manner previously described. Full movement of arm 480 can take place at this time because the amount keys are restored to their undepressed positions

at the end of the preceding addition operation and the flange 516 is therefore no longer in position to obstruct the movement of the finger 515. Then, upon the return to the right of the arm 478 in its moved clockwise position, the shoulder 561 engages the stud 560 and rocks the lever 473 and the plate 471 in a counter-clockwise direction near the end of this first machine cycle of the sub-total operation.

During this first machine cycle of the sub-total-taking operation, the engaging lever 388 will be rocked, by the pitman 399 (Fig. 15) first clockwise to disengage the totalizer pinions 392 from the racks 262 and then clockwise to again engage those pinions with said racks. As the totalizer is disengaged, any and all tripped transfer devices are restored to normal, just as during the first machine cycle of the previously described total-taking operation.

When the plate 471 is rocked counter-clockwise near the end of the first machine cycle of the sub-total operation as above described, it will cause the stud 469 to move about the stud 470 in an arcuate path to the right from the position shown in Fig. 15. This movement of the stud 469 will cause the link 475 to move upwardly and rock the bell crank 404 counter-clockwise, and will cause the upper end of the link 475 to move to the right (Fig. 15) to place a roller 562, carried by the upper end of the link 475, in a position to engage the pitman 398 when the pitman is released by the counter-clockwise movement of the bell crank 404.

The roller 562 is so located on the link 475 that, when the link has moved the roller to the right in a sub-total operation, the roller will be in a position to allow the spring 402 to move the pitman out of engagement with the stud 398 but will not allow the pitman to be moved far enough for the notch 513 therein to engage the stud 514.

Now, at the beginning of the second machine cycle of the sub-total operation, when the pitman 398 is moved to the left (Fig. 15) by the bell crank 400, the totalizer engaging lever 388 is not rocked, and consequently the totalizer pinions 392 remain engaged with the racks 262 while they are moved forwardly to clear the totalizer and set the diverging levers 271 differentially accordingly. The printer, described later, is then operated to print each sub-total.

Now the bell crank 400 restores the pitman 398 to normal, and, as the roller 562 prevents the notch 513 of the pitman from engaging the stud 514 in the lever 390, there is no movement of the lever 388 during the return movement of the pitman 398, so that, at the end of the second machine cycle of the sub-total operation, the totalizer is still in engagement with the racks 262. Then the restoring bail 281 restores the rack levers 281, thus adding back into the totalizer the amount taken therefrom, which has just been printed. The diverging levers 271 are also restored, as previously described. Also during the second machine cycle, the latch 453 is released from the fingers 450 and 451, thus permitting the bell crank 404 to be restored to normal in the same manner as described in connection with the total-taking operation.

During this sub-total operation, and at the beginning of the second machine cycle thereof, the spring 482 rocks the arm 480 clockwise until it is stopped by the flange 516 (Fig. 14); as during the second machine cycle of the total-tak-

ing operation, explained above. This short movement of the arm 480 is sufficient to draw the arm 478 to the left, so that the shoulder 561 is released from the stud 560, whereupon the spring 487 again centralizes the arm 478; that is, disengages the shoulder 561 from the stud 560. Consequently, when the link 402 is restored during this second machine cycle of the sub-total operation, the arms 478 and 480 will be restored to their normal positions.

Also during the above sub-total operation, the zero stop pawls 133 are controlled by the link 535 to control the stop bars 276 and to cooperate with the anti-slam racks 544 in exactly the same manner as during the previously described total-taking operation, though their cooperation with the anti-slam racks 544 is an idle operation in sub-total-taking operations, inasmuch as the totalizer wheels are not disengaged from the actuating racks at the middle of the cycle, as they are in the case of a total-taking operation.

Non-add control of the totalizer

At times, it may be desirable to print a list of numbers without adding them into the totalizer. In order to do this, after the totalizer is disengaged from the actuating racks 262, it is held disengaged while the racks are moved forwardly with the diverging levers 271 and held disengaged upon the restoration of the rack levers 261 and the diverging levers 271. Consequently, the amount which was set up on the keyboard may be printed by the printing means to be described later, but it will not be added into the totalizer. Such an operation is initiated by the depression of the non-add key 163 (Figs. 1 and 6). The mechanism operated under the control of the non-add key 163 will now be described.

Pivoted on a stud 570 carried by the side frame 31 is a lever 571 having a pin 572 lying in the path of the bottom end of the non-add key stem 168 (Fig. 19). A stud 573, carried by a plate 574 pivoted on the stud 446, is normally held against the end of the lever 571 by a spring 575 stretched between the plate 574 and the previously described bell crank 404. The plate 574 is also held by the spring 575 against a pin 576 on a plate 577 pivoted on the stud 446. A stud 578 carried by the plate 577 projects into a slot 579 (Fig. 16) of the plate 449, which is formed by a finger 589 integral with said plate 449. Pivoted to the plate 577 is a link 581 (Fig. 19), which is also pivoted to an arm 582 pivoted on the rod 309 adjacent the side frame 31. A spring 583 normally holds a finger 584 of the arm 582 against a stop stud 585 carried by the side frame 31 and also acts to hold the stud 578 in contact with the finger 584.

Upon depression of the non-add key 163, the bottom end of its stem 168 contacts the stud 572 and rocks the lever 571 clockwise, thus rocking the plate 574 clockwise, and moves a finger 586 of the plate 574 into the path of movement of a roller 597 secured to the arm 420, which, it will be remembered, is fast on the drive shaft 100. Consequently, when the arm 420 is rocked counter-clockwise, the roller 597 engages the upper surface of the finger 586 and rocks the plate 574 still farther clockwise, whereupon the stud 573, by its contact with the under side of the plate 577, rocks said plate clockwise against the tension of the spring 583 to raise the link 581. At the same time, the stud 578 rocks the arm 75 449 to position the finger 451 above the path

of movement of the flange 452 of the latch lever 453, thereby enabling the latch to be rocked by its spring 455 so as to release the motor for operation.

Just prior to this movement of the link 581, the pitman 399 has been moved to the left, in the manner previously described, to rock the totalizer engaging and disengaging lever 388 clockwise to disengage the totalizer pinions 302 from the actuating racks 262 in the manner previously described. This disengaging movement of the totalizer has placed a finger 588 of the coupling pawl 395 above a stud 589 carried by a finger 590 integral with the link 581. Therefore, as the link 581 is raised in the manner described above, the stud 589 engages the finger 588 and rocks the coupling pawl 395 counter-clockwise to disengage it from the stud 396 of the engaging lever 388.

With the coupling pawl 395 disengaged from the stud 396, when the pitman 399 is moved to the right (Fig. 15) to its normal position, it will merely rock the lever 390 counter-clockwise without moving the totalizer pinions 302 back into engagement with the actuating racks 262, and consequently, when these racks are restored to their normal positions, the amount which was set up on the keyboard and under which amount the racks 262 were differently positioned will not be added into the totalizer upon the restoration of those racks.

However, since the diverging levers 271 were differentially positioned, the amount which was set up on the keyboard is printed before the diverging levers 271 are restored to their normal positions, which, it will be recalled, occurs at the same time the actuating racks 262 are restored to their normal positions.

When the lever 390 is rocked counter-clockwise, the coupling pawl 395 is prevented from rocking clockwise under the action of its spring 397 by means of a stud 591 (Fig. 19) on the pawl which contacts the top surface of the lever 390.

After the printing has taken place and as the arm 420 is restored clockwise to its normal position by the drive shaft 100, the roller 587 leaves the top surface of the finger 586, whereupon the spring 583 lowers the link 581, thus rocking the plate 577 counter-clockwise. This allows the arm 449 to be restored to its initial position with the finger 451 once more located in blocking position when the latch 453 is restored by the roller 144 near the end of the machine cycle and permits the spring 397 to rock the coupling pawl 395 clockwise until the stud 591 contacts the top of the lever 390. The non-add key 163 is then released in the manner previously described, whereupon the spring 575 (Fig. 19) rocks the plate 574 and the finger 586 back to the position shown in this figure. Near the very end of the operation, the arm 420 (Fig. 15) then contacts the stud 419 of the totalizer engaging lever 388 and rocks said lever counter-clockwise, whereupon the cam slot 387 reengages the totalizer pinions 302 with the actuating racks 262. During this counter-clockwise movement of the lever 388, the pin 396 contacts the end of the coupling pawl 395 and rocks the pawl slightly counter-clockwise against the tension of its spring 397 until the stud 396 has passed the hook on the end of the pawl, whereupon the spring 397 will again rock the pawl clockwise to its normal position, which is shown in Figs. 15 and 19.

PRINTER

The printing mechanism associated with the present invention will now be described, and, since parts of this printing mechanism are substantially the same as those shown in the above-mentioned Peters Patent No. 1,386,021, those parts will be but briefly described.

Platen and frame

A platen 600 (Figs. 5 and 11) is secured to a shaft 601 mounted in platen supporting plates 602 and 603 secured to an angle bar 604, which is adjustably mounted for front and back movement on a pair of brackets 605 (Fig. 8) (only one of which is shown), which brackets are secured to the side frames 30 and 31. A tie bar 606, secured to the plates 602 and 603, properly spaces the plates near their top edges. Secured to the shaft 601, at each end thereof, is a knob 607, by means of which the shaft 601 and the platen 600 may be turned in either direction by hand in the usual manner. Cooperating with the platen 600 is the usual pair of compression rolls 608 mounted in a movable frame (not shown) adapted to be moved by the operator when desirable or necessary by a lever 609 (Fig. 8).

Tape

Mounted on a rod 610 supported by the plates 30 602 and 603 is a supply roll 611, from which a tape 612 is adapted to be fed first upwardly over a guide plate 613 and thence downwardly between the platen 600 and the compression rolls 608, then upwardly between the platen and a guide 614, which guide carries a serrated transparent tear-off bar 615.

Since the tape 612 is not as wide as the platen, it is guided by a pair of plates 616. The guide 614 has an opening through which the type, later described, is adapted to be projected to make a print on the tape 612.

Tape feeding mechanism

After the printing of each of the items, the sub-total, or the total, the tape 612 is advanced so that the last printed amount is visible to the operator. Also during the first machine cycle of each total or sub-total operation, the tape 612 is advanced one step to separate the total or sub-total from the last item printed.

This feeding mechanism for the tape 612 will now be described with particular reference to Figs. 5 and 18. Secured to the shaft 601 is a feed ratchet 620, with which cooperates feed pawl 621 pivoted on a stud 622 carried by an arm 623, which is pivoted on a rod 624 supported by the machine side frames 30 and 31. The pawl 621 has an arm 625 normally held in contact with a stud 626 on the side frame 30 by a spring 627 to keep the nose of the pawl 621 normally away from the ratchet 620. An alining stud 628, carried by a lever 629, is held in engagement with the ratchet 620 by a spring 630, so as to maintain the platen 600 and consequently the tape 612 in proper position at all times. When the ratchet 620 is advanced either one step or two steps, as will be described hereinafter, the stud 628 merely slides idly over the edges of the teeth 620 of the ratchet.

The arm 623, described above, lies on the inside of the side frame 30 and has a bail 631, by means of which the arm 623 is secured to an arm 632 also pivoted on the rod 624 on the outside of the side frame 30. This arm 632 carries a screw stud 633, upon which is pivoted a pitman 634.

having a slot 635 surrounding a stud 816 in the side frame 30. The lower end of the pitman 634 is held, by a spring 637, in contact with a roller 636 carried by the drive plate 78, previously described, which is secured to the drive shaft 76.

When the shaft 76 and consequently the plate 78 are rocked counter-clockwise, the roller 636 is moved away from the bottom of the pitman 634, whereupon the spring 637 rocks the arm 632 and consequently the arm 623 clockwise to lower the nose of the pawl 621. As the arm 623 is lowered, the spring 627 rocks the pawl 621 clockwise, so that it will engage the ratchet 620. Now, as the cam plate 78 is rocked clockwise to its normal position, the roller again engages the bottom of the pitman 634 and moves said pitman upwardly, thus rocking the arms 632 and 623 counter-clockwise to raise the pawl 621, which turns the ratchet 620 and consequently the platen 600.

The arm 632 is adapted to be moved clockwise by the spring 637 either one step or two steps of movement to lower the pawl 621 either one tooth or two teeth relative to the ratchet 620. As shown in Fig. 18, the parts are in the positions whereby the pawl 621 will be lowered two steps.

This one or two steps of movement of the pawl 621 is controlled by the following mechanism. The arm 632 has a bent-over flange 638, which lies directly above a plate 639 pivoted on the rod 470 carried by the side frames 30 and 31. This plate 639 has three steps, 641, 642, and 643, which steps are varying distances from the center of the rod 470. Secured to this plate by means of a bail 644 is a manually operable lever 645.

When the lever 645 is in the position shown in Fig. 18, the shoulder 641 is below the flange 638, and consequently the arm 632 can be moved downwardly a distance sufficient to move the pawl 621 two tooth spaces on the ratchet 620. Therefore, when the pawl 621 is restored upwardly to its normal position, the tape 612 will be advanced two steps of movement. The lever 645 and the plate 639 are held in the positions shown in Fig. 18 by a notched alining arm 646 (Fig. 2), which is pivoted on the rod 624 and connected by a bail 647, which in turn is connected to another arm 648 pivoted on the rod 624, as shown in Fig. 5. A torsion spring 649 holds the notched arm 646 up against an alining pin 650 carried by the lever 645. When the lever 645 is moved one step to the right, the shoulder 642 is beneath the flange 638, and consequently the pawl 621 at this time can be lowered only one step to feed the tape 612 one step of movement. When the lever 645 is moved to the right, its extreme distance, then the step 643 of the arm 639 is positioned beneath the flange 638, which prevents any downward movement of the arm 632 and consequently of the pawl 621, and therefore there will be no feeding movement of the tape 612.

Amount type bars

Since all of the amount type bars are identical, a description of one will suffice for all. Referring to Figs. 2 and 5, there is pivoted to the arm 272 of the diverging lever 271 a link 661, which is also pivoted on a pin 662 carried by a type bar 663. A spring clip 664 holds the link 661 on the pin 662. The type bar 663 is guided for vertical movement between guide plates 665 and 666 secured to plates 667 and 668 (see also Fig. 11), which are mounted on the shaft 76 and the rod 470 and form a framework for the type bars, the hammers, and other mechanism in connec-

tion with the making of the prints on the tape 612. Each type bar 663 carries ten type 669 of the usual type, which are held in position on the type bar by a retaining plate 670. These type bars carry the characters 0 to 9 inclusive and are adapted to be moved to the right by a printing hammer later described. A spring (not shown) holds the type 669 in the positions shown in Fig. 2.

When the diverging lever 271 is set differentially under control of the keys 120 or under control of the totalizer pinion 302 during total or sub-total taking operations, the arm 272 is rocked counter-clockwise a corresponding distance, thus raising the type bar 663 to position the proper one of the type 669 opposite the printing line so that such amount may be printed on the tape 612, which lies against the platen 600.

Symbol type bar

There is also in the present machine a type bar known in the art as a symbol type bar, which carries type to designate, by printing, the various types of operation through which the machine is being put.

This symbol type bar 671 (Fig. 19) is mounted for vertical movement between the guide plates 665 and 666. It carries four type 672, 673, 674, and 675. The type 672 has a minus sign (-) indicating subtract, type 673 has an "S" indicating sub-total, type 674 has an asterisk (*) indicating total, and the type 675 has a number sign (#) indicating non-add. This type bar 671 is pivotally connected to an arm 676, which is pivoted on a long stud 677 carried by the side frame 31. A bail 678 connects the arm 676 with an arm 679 having a stud 680 held against a finger 681 of a lever 682 by a spring 683. This lever 682 is pivoted on a stud 684 supported by the right side frame 31.

The means for moving the symbol bar 671 different distances to bring the various type 672 to 675 inclusive opposite the printing line on the platen, so that the various characters may be printed on the tape 612, will now be described.

During adding operations, the symbol bar 671 is not moved, since there is no symbol printed opposite the various items as they are printed on the tape 612.

During subtract operations, the bar 671 is raised one step by the following mechanism, to bring the type 672 opposite the printing line.

Secured to the drive shaft 76 (Fig. 10) is an arm 690 connected by a link 691 to an arm 692 secured to a shaft 693, which is supported by the plates 667 and 668. Also secured to the shaft 693 is an arm 694 carrying a stud 695, upon which is pivoted a coupling latch 696 having a flange 697 and also having a stud 698 (Fig. 11) held by a spring 699 in contact with an arm 700 pivoted on the rod 470. This arm 700 is connected by a bail 701 to an arm 702, also pivoted on the rod 470. Pivoted to the arm 702 is a link 703, which is pivoted to a bell crank 704 mounted on a stud 705 carried by the frame 30. A spring 706 holds the bell crank 704 in contact with a stud 707 on the previously described arm 373, which, it will be recalled, is rocked clockwise upon subtract operations.

Clockwise movement of this arm 373, through the bell crank 704, the link 703, the arm 702, and the bail 701, rocks the arm 700 clockwise to position a surface 708 thereon opposite the stud 698 on the coupling latch 696, whereupon the spring 699 rocks the latch counter-clockwise,

so that its flange 697 will be moved into a notch 709 of a cam plate 710 pivoted upon the shaft 693. The cam 710 cooperates with a roller 711 carried by a vertical slide 712 having a horizontal plate 713, which is notched to be guided by the plate 667, as shown in Fig. 5. Integral with this horizontal plate 713 of the slide 712 is an arm 714 having a stud 715 engaged by a forked arm 716 connected to a sleeve 717 loosely mounted on the rod 470. Also connected to the sleeve 717 is a forked arm 718 (Fig. 5) engaging a stud 719 on an arm 720 integral with a horizontal plate 721, which in turn is secured to a vertical slide, not shown, but like the slide 712 shown in Fig. 11. The arm 720 (Figs. 5 and 19) has secured to it a plate 722 with a flange 723, which lies beneath a flange 724 of a plate 725 secured to the symbol type bar 671.

During a subtract operation, after the depression of the subtract key 162 and after the coupling latch 696 has been released by the arm 700, the arm 690 (Fig. 10), through the link 691, rocks the arms 692 and 694 clockwise, and, since the flange 697 on the latch 696 is engaged with the notch 709 of the cam 710, said cam will be rotated clockwise along with the arms 692 and 694, whereupon, through its engagement with the roller 711, it will raise the slide 712, which, through the arms 714, 716, 718, and 720, will cause the flange 723 to contact the under side of the flange 724 and raise the symbol type bar 671 one step to bring the subtract type 672 into printing position.

When the shaft 16 (Fig. 10) and the arm 690 are restored clockwise to their normal positions, the link 691 rocks the arms 692 and 694 counter-clockwise to their normal positions; thereupon the slide 712 and the arms connected thereto, including the arm 720, will be permitted to move downwardly into their normal positions by gravity. To positively insure that these parts are restored, the slide 712 has a stud 726 projecting into a slot 727 of the cam 710, so that, if the parts should fail to move down under the force of gravity alone, the side of the cam slot 727 will, by its contact with the stud 726, move the slide 712 and the connected parts downwardly to their normal positions, this being occasioned by the flange 697 in the notch 709 of the cam 710. After the cam 710 is restored to its normal position and after the arm 723 is restored counter-clockwise to its normal position, the spring 706 will rock the bell crank 704 counter-clockwise, whereupon the link 703 will raise the arm 700 to the position shown in Fig. 11 to disengage the coupling latch 696 from the notch 709 of the cam 710.

During sub-total operations, the symbol bar 671 is moved up two steps to bring the type 673 carrying the letter "S" opposite the printing line. This is caused by a stud 730 (Fig. 19), which is carried by the plate 471. It will be recalled that during sub-total operations the plate 471 is moved counter-clockwise, whereupon the stud, by its engagement with a finger 731 of the lever 682, will rock said lever clockwise, thus moving the finger 681 of the lever 682 away from the stud 680, and the spring 683 will rock the arms 679 and 676 to raise the symbol type bar 671 to the second position, so that the type bar 673, bearing the character "S," will be in printing position. As the plate 471 is restored to its normal position, the spring 683 will rock the lever 682 counter-clockwise, whereupon the finger 731

will follow the stud 730 back to the position shown in Fig. 19.

To raise the symbol bar 671 to the third position to bring the type 674, bearing the asterisk, opposite the printing line, the lever 682 carries a stud 732 in the path of the plate 471. It will be recalled that during total operations the plate 471 is moved clockwise, whereupon a surface 733 of the plate 471 contacts the stud 732 and rocks the lever 682 clockwise to again allow the spring 683 to raise the symbol bar 671, this time three steps of movement to bring the type bar 674 opposite the printing line. When the plate 471 is restored to normal, the spring 683 again restores the lever 682 to allow the symbol bar 671 to restore to its normal position.

During non-add operations, the symbol bar 671 is moved up four steps to bring the bar 675, bearing the number sign, opposite the printing line. This is effected by a stud 734, which, as the link 581 is raised during non-add operations, in the manner previously described, by its contact with a finger 735 on the lever 682, rocks said lever 682 clockwise to again allow the spring 683 to raise the symbol bar 671 four steps of movement to bring the type 675 opposite the printing line.

Hammer mechanism

There is one hammer 740 (Fig. 2) for each of the type bars 663 and one for the symbol type bar 671. As all of these hammers are alike, and as the mechanism for operating each of them is the same, a description of one of the hammers and its operating mechanism will suffice. The hammer 740 is pivoted on a rod 741 carried by the frame plates 667 and 668. A spring 742 normally urges the hammer clockwise, but is normally prevented from such rocking movement because a hook 743 on the hammer 740 is beneath a latch 744, which is pivoted on a rod 745 carried by the plates 667 and 668. A spring 746 normally holds the latch 744 in engagement with the hook 743. The type bar 663 carries a stud 747, which engages and holds a tripping finger 748 pivoted on a rod 749 in the position shown in Fig. 2, under tension of a spring 751. When the type bar 663 is raised above the zero position, the spring 751 rocks the tripping finger 748 counter-clockwise to position it directly behind a shoulder 752 of the latch 744.

The rod 749, which supports the tripping finger 748, is carried by a pair of arms 750 pivoted on the rod 741 and is moved to the left (Fig. 2) at the proper time, whereupon the finger 748, by its contact with the shoulder 752, releases the latch 744 from the hook 743 of the hammer 740, after which the spring 742 rapidly rocks the hammer 740 clockwise, whereupon it strikes the front of the type 669, which has been selected for printing, to force it quickly against a ribbon 753 (Fig. 11) to make a legible impression on the tape 612, which is backed up by the platen 600. The hammers 740 are guided in their movement by a comb 754 secured to the plates 667 and 668.

The means for rocking the rod 749 to operate the tripping fingers 748 comprises the following mechanism. Secured to the drive shaft 16 are two arms 760 (only one of which is shown) each having a stud 761, which, when the shaft 16 is rocked counter-clockwise, engages a finger 762 of each of the arms 750, thus rocking the arms clockwise to move the rod 749 and the tripping finger 748 to the left in the manner previously described and for the purpose there stated. As

the shaft 76 restores clockwise to its normal position, a spring 763 (one being attached to each of the fingers 762) restores the arms 759 counter-clockwise to their normal positions.

After the hammers 740 have operated the selected type 669 to make a legible impression, a restoring bail or rod 764 (Figs. 2 and 10), carried by the arms 692 and 694, first having been moved away from the upper sides of the hammers upon the clockwise movement of the arms 692 and 694, again engages the top edges of the hammers 740 and restores them positively to their normal positions, shown in Fig. 2, when the shaft 76 is rocked clockwise to its normal position to rock the arms 692 and 694 counter-clockwise to their normal positions.

When the type bar 663 is raised to the zero position only under control of the zero stop 133, the finger 748 is not lowered far enough to get behind the shoulder 152, and therefore, when the rod 749 is moved forwardly, the latch 744 is not tripped and the hammer 740 cannot operate. However, it is desirable to print zeros to the right of the highest order significant number, and therefore the latch 744 has the usual bent-over finger 765, which is in the path of the latch of next higher order, and consequently all latches 744 to the right—that is, latches 744 of lower orders—will be tripped by their next higher finger 765 from any denomination in which a significant number is set up, as disclosed in the Peters Patent No. 1,386,021.

Thus, during the first machine cycle of a total or a sub-total operation, since the zero stops 133 control the type bars at that time, none of the hammers 740 will be tripped, and consequently there is no printing during such first machine cycles.

Ribbon mechanism

The ribbon 753, above mentioned, is carried by a pair of spools 770 (Figs. 5 and 11) mounted in the usual manner on the horizontal plates 713 and 721 of the vertical slides 712. The ribbon 753 is passed around the front ends of the arms 714 and 720 so as to be in position between the type 669 and the tape 612.

None of the feeding mechanism for the ribbon has been shown herein, as this is old and well known in the art and may be found by referring to the Peters Patent No. 1,386,021, it being sufficient to state that the ribbon is fed from one spool to another and automatically reversed when one of the spools is substantially empty.

Ribbon shifting for subtract

The ribbon 753 is usually a polychrome ribbon, having the upper part black and the lower part red, so that all items subtracted may be printed in red. In order to do this, it is necessary to shift the spools vertically to bring the red portion of the ribbon opposite the type 669. Since the plates 713 and 721 are raised in the manner previously described during subtract operations, to cause the symbol type bar 671 to be raised to print a subtract sign whenever the subtract key 162 is depressed, the ribbon spools will be raised at the same time to bring the red portion of the ribbon 753 opposite the type 669, so that the amount subtracted will be printed in red instead of black. At the end of the subtract operation, when the slides 712 and the plates 713 and 721 thereof are moved downwardly to their normal positions, the spools 770 will be lowered at the same time, so that the black section of the ribbon 753 will again

be opposite the type 669 for printing the items, the totals, and the sub-totals in black.

To protect the ribbon spools from dirt and also to make a better-looking cabinet or casing, the spools are covered by a pair of plates 771 (Fig. 1).

Non-print mechanism

Whenever it is desired to add a list of items or subtract any number from the totalizer, and at the same time non-print those numbers, the lever 645 is moved to its extreme right-hand position, so that the surface 643 on the arm 639 is below the flange 638 to prevent any movement of the feed pawl 621 and the feed ratchet in the manner previously described. It will be recalled that the alining arm 646 is contacted by the pin 650 of the lever 645. This alining arm is so shaped that, when the lever 645 is moved clockwise to its extreme position, the arm 646 will be rocked clockwise, and the pin 650 will at that time engage a notch 713 on the arm 646, thus holding the arm 646 in its moved clockwise position. Secured to the bail 647 of the arm 646 is a latch 714, the forward end of which, when the arm 646 is moved clockwise in the manner previously described, and so held by the pin 650, is moved in front of the upper ends of the hammers 740, thus preventing movement of the hammers even though the latches 744 are released therefrom by the movement of the rod 749 in the manner previously described. Since the hammers 740 are prevented from clockwise movement, of course, no printing will be made of the amounts set up on the keyboard, which may be either added to or subtracted from the totalizer.

Operation

Since the complete operation of all parts described has been given in connection with the descriptions of those parts under the various headings and sub-headings, it is not thought necessary to go into any description of the operation of the machine at this time, as it would serve no further purpose.

While the form of mechanism herein shown and described is admirably adapted to fulfill the objects primarily stated, it is to be understood that it is not intended to confine the invention to the one form of embodiment disclosed herein, for it is susceptible of embodiment in various forms all coming within the scope of the claims which follow.

What is claimed is:

1. In a machine of the class described, adapted to make one-cycle adding operations and two-cycle sub-total operations, the combination of power means for giving the machine cycles of operation; normally ineffective means for initiating operation of said power means; amount determining devices; a totalizer; actuators operable under control of said devices to enter amounts in said totalizer; totalizer engaging and disengaging means; sub-total-taking control means operable to cause a sub-total to be taken from said totalizer; and a manually depressible member for rendering said initiating means effective to cause said power means to drive the machine through a one-cycle operation to cause an amount to be entered into said totalizer when said member is operated and immediately released by the operator; means operable to maintain said initiating means effective to cause said power means to continue to drive the machine after said manually depressible member has been released; and means controlled by said manually depre-

sible member for causing said maintaining means and said sub-total-taking control means to be operated when said member is held depressed throughout said one-cycle amount-entering operation and through a certain portion of the next succeeding cycle to thereby cause said amount-entering operation to be immediately followed by an automatic two-cycle sub-total-taking operation.

2. In a machine of the class described, adapted to make one-cycle adding operations and two-cycle sub-total operations, the combination of power means for giving the machine cycles of operation; normally ineffective means for initiating operation of said power means; amount determining devices; a totalizer; actuators operable under control of said devices to enter amounts in said totalizer; totalizer engaging and disengaging means; sub-total-taking control means for controlling said engaging and disengaging means so as to cause said totalizer to be engaged with and disengaged from said actuators at the proper time in the machine cycle to cause a sub-total to be taken from said totalizer; and a manually depressible member for rendering said initiating means effective to cause said power means to drive the machine through a one-cycle operation to cause an amount to be entered into said totalizer when said member is operated and immediately released by the operator; means operable to maintain said initiating means effective to cause said power means to continue to drive the machine after said manually depressible member has been released; and means controlled by said manually depressible member for causing said maintaining means to be operated and said sub-total-taking control means to be rendered effective when said member is held depressed throughout said one-cycle amount-entering operation and through a certain portion of the next succeeding cycle to thereby cause said amount entering operation to be immediately followed by an automatic two-cycle sub-total-taking operation.

3. In a machine of the class described, adapted to make one-cycle adding operations and two-cycle sub-total operations, the combination of power means for giving the machine cycles of operation; normally ineffective means for initiating operation of said power means; amount determining devices; a totalizer; actuators operable under control of said devices to enter amounts in said totalizer; totalizer engaging and disengaging means; sub-total-taking control means for controlling said engaging and disengaging means so as to cause said totalizer to be engaged with and disengaged from said actuators at the proper time in the machine cycle to cause a sub-total to be taken from said totalizer; a manually depressible member for rendering said initiating means effective to cause said power means to drive the machine through a one-cycle operation to cause an amount to be entered into said totalizer when said member is operated and immediately released by the operator; means operable to maintain said initiating means effective to cause said power means to continue to drive the machine after said manually depressible member has been released; means controlled by said manually depressible member for causing said maintaining means to be operated and said sub-total-taking control means to be rendered effective when said member is held depressed throughout said one-cycle amount-entering operation and through a certain portion of the next

succeeding cycle to thereby cause said amount-entering operation to be immediately followed by an automatic two-cycle sub-total-taking operation; and means operable by said amount determining devices to prevent said normally ineffective means from being rendered effective under the control of said manually depressible member during said one-cycle operation.

4. In a machine of the class described, adapted to make one-cycle add operations and two-cycle total operations, the combination of a normally inoperative main operating mechanism; a group of depressible amount determining devices; a totalizer; actuators therefor controlled by said devices; totalizer engaging and disengaging means; controlling means for said engaging and disengaging means; a manually operable member to render said mechanism operative to cause two successive cycles of operation of the machine; a plurality of rockable devices intermediate said controlling means and said member and actuated by the latter to operate the controlling means to cause the engaging and disengaging means to control the totalizer to cause a total to be taken therefrom when said operating mechanism is rendered operative by said member; means controlled by the amount determining devices for preventing said rockable devices from causing the engaging and disengaging means to control the totalizer to cause a total to be taken when any of the amount determining devices are depressed; and a device actuated by said member and cooperating with said preventing means to prevent operation of any of said amount determining devices after operation of said member.

5. In a machine of the class described, the combination of amount determining devices; a totalizer; actuators therefor; means connected to said actuators and cooperating with said devices to determine the extent of movements of said actuators; totalizer engaging and disengaging means; controlling means for said engaging and disengaging means; zero stops controlled by said amount determining devices for preventing movement of said actuators when the amount determining devices remain unoperated; total-taking control means for controlling said controlling means and said zero stops to cause a total to be taken from said totalizer; a toothed member carried by each of the means connected to the actuators; and means on said zero stops adapted to cooperate with the teeth on said members to prevent movement of said actuators after disengagement of said totalizer from the actuators after the total has been taken therefrom.

6. In a machine of the class described, adapted to make one-cycle add operations and two-cycle total operations, the combination of a normally inoperative main operating mechanism; amount determining devices; a totalizer; actuators therefor; means connected to said actuators and cooperating with said devices to determine the extent of movements of said actuators; totalizer engaging and disengaging means; controlling means for said engaging and disengaging means; a manually operable member to render said mechanism operative to cause two successive cycles of operation of the machine; a plurality of rockable devices intermediate said controlling means and said member and actuated by the latter to operate the controlling means to cause the engaging and disengaging means to control the totalizer to cause a total to be taken therefrom when said operating mechanism is rendered operative by said member; a toothed member car-

ried by each of the means connected to the actuators; means adapted to cooperate with said toothed members to prevent movement of said actuators after disengagement of said totalizer from the actuators after the total has been taken therefrom; and means connected to the controlling means for the engaging and disengaging means for controlling the means which cooperates with said toothed members.

7. In a machine of the class described, adapted to make one-cycle add operations and two-cycle total operations, the combination of a normally inoperative main operating mechanism; amount determining devices; a totalizer; actuators therefor; means connected to said actuators and cooperating with said devices to determine the extent of movements of said actuators; totalizer engaging and disengaging means; controlling means for said engaging and disengaging means; a manually operable member to render said mechanism operative to cause two successive cycles of operation of the machine; a plurality of rockable devices intermediate said controlling means and said member and actuated by the latter to operate the controlling means to cause the engaging and disengaging means to control the totalizer to cause a total to be taken therefrom when said operating mechanism is rendered operative by said member; a toothed member carried by each of the means connected to the actuators; means adapted to cooperate with said toothed members to prevent movement of said actuators after disengagement of said totalizer from the actuators after the total has been taken therefrom; means connected to the controlling means for the engaging and disengaging means for controlling the means which cooperates with said toothed members; and means for disconnecting the means connected to the controlling means from said controlling means to control the means which cooperates with the toothed members.

8. In a machine of the class described, the combination of a normally inoperative main operating mechanism; means for rendering said mechanism operative; a member for latching said means in a normal ineffective position; means including a plurality of manually operable members for operating said latching member to release said means to render said mechanism operative; means common to all of said manually operable members for locking any member which has been operated in its operated position and prevent operation of the remaining members; and means actuated by the means for rendering the main operating mechanism operative for operating said locking means upon operation of said rendering means.

9. In a machine of the class described, the combination of a normally inoperative main operating mechanism; means for rendering said mechanism operative; a member for latching said means in a normal ineffective position; means including a plurality of manually operable members for operating said latching member to release said means to render said mechanism operative; means common to all of said manually operable members for locking any member which has been operated in its operated position and prevent operation of the remaining members; and a single member connecting said locking means to said rendering means and actuated by the latter to operate said locking means.

10. In a machine of the class described, the combination of a normally inoperative main operating mechanism; means for rendering said mechanism operative; a support; a latch device carried by said support to retain said rendering means ineffective; means including a plurality of manually operable members all slidably mounted on said support for operating said latch device and thereby causing said main operating mechanism to be rendered operative; means slidably mounted on said support and common to all of said manually operable members to lock any operated one of the manually operable members in an operated position and lock all the remaining members in their normal positions; and a lever pivoted on said support and connected directly at one end to said slidably mounted means and at the other end to said rendering means and actuated by the latter to operate the slidably mounted means upon operation of said latch device.

11. In a machine adapted to perform adding and total-taking operations, the combination of amount determining means; a normally inoperative main operating mechanism; a plurality of manually operable members any one of which, when operated, renders said mechanism operative and controls the kind of operation to be performed; a common support for all of said members; normally ineffective locking means carried by said support; means for rendering said locking means effective during each operation of said main operating mechanism; means carried by certain of said members for cooperating with said locking means to cause any of said certain members which are operated to be locked in operated position and to cause any of said certain members which are unoperated to be locked in normal position by said locking means during an operation of said main operating mechanism; a device operatively connected with another of said members and cooperating with said locking means to cause the latter member to be locked in operated position by said locking means during an operation of said main operating mechanism; and means operated by any of said amount determining means for preventing operation of said device.

12. In a machine adapted to perform adding and total-taking operations, the combination of amount determining means; a normally inoperative main operating mechanism; a plurality of manually operable members any one of which, when operated, renders said mechanism operative and controls the kind of operation to be performed; a common support for all of said members; normally ineffective locking means carried by said support; means for rendering said locking means effective during each operation of said main operating mechanism; means carried by certain of said members for cooperating with said locking means to cause any of said certain members which are operated to be locked in operated position and to cause any of said certain members which are unoperated to be locked in normal positions by said locking means during an operation of said main operating mechanism; a device operatively connected to another of said members and cooperating with said locking means to cause the latter member to be locked in operated position by said locking means during an operation of said main operating mechanism; and a member carried by said support and adapted to be moved into the path of movement 75 of said device upon operation of any of said

amount determining means to prevent operation of said device.

13. In a machine adapted to perform adding and total-taking operations, the combination of amount determining means; a normally inoperative main operating mechanism; a plurality of manually operable members any one of which, when operated, renders said mechanism operative and controls the kind of operation to be performed; a common support for all of said members; normally ineffective locking means carried by said support; means for rendering said locking means effective during each operation of said main operating mechanism; means carried by certain of said members for cooperating with said locking means to cause any of said certain members which are operated to be locked in operated position and to cause any of said certain members which are unoperated to be locked in normal position by said locking means during an operation of said main operating mechanism; a device operatively connected with another of said members and cooperating with said locking means to cause the latter member to be locked in operated position by said locking means during an operation of said main operating mechanism;

5 10 15 20 25

and means carried by said support and cooperating with said device in the operated position of said device for preventing operation of any of said amount determining means.

HARRY L. LAMBERT.
